UNITED STATES PATENT OFFICE.

WINTHROP K. HOWE, OF ROCHESTER, NEW YORK, ASSIGNOR TO GENERAL RAILWAY SIGNAL COMPANY, OF GATES, NEW YORK, A CORPORATION OF NEW YORK.

SYSTEM FOR AUTOMATICALLY GOVERNING RAILWAY TRAFFIC.

Application filed July 3, 1916, Serial No. 107,355. Renewed November 23, 1925.

To all whom it may concern:

Be it known that I, WINTHROP K. HOWE, a citizen of the United States, and a resident of the city of Rochester, in the county of Monroe and State of New York, have invented a new and useful System for Automatically Governing Railway Traffic, of which the following is a specification.

This invention relates to systems for automatically controlling railway traffic and more particularly to such systems in which the signals furnished for the guidance of the engineer or motorman of the train are operated or displayed directly in front of him in the cab, and in which suitable provisions are made whereby the speed of the train will be automatically controlled if the motorman or engineer should for any reason fail to observe and obey these signals.

It has heretofore been recognized that the different types of the well known block signaling systems in which signals are displayed at certain fixed points along the track do not afford all of the safety and protection desired for various reasons. One reason is that, even if absolute accuracy and reliability in the operation of these fixed signals is obtained, conditions are often such that it is very difficult for the engineer of the train to see these signals clearly and be able to unmistakably understand their significance. Furthermore, experience has demonstrated that the human machine has an appreciable percentage of failure, and that, while the reliability of an engineer may be equal to or greater than the reliability of automatic mechanism, it is desirable to supplement the vigilance and reliability of the engineer by automatic mechanism. The solution of this problem of an automatic train control system involves a large number of factors; but in general it may be said that in devising such a system it is desirable to observe and satisfy the exacting requirements which have been found by long experience to be essential to a safe railway signaling system; further, to obtain the best safety in the operation of the trains without unnecessarily limiting the facility of their movements; and finally to satisfy the requirements and conditions for simple, reliable and practical operation.

With these considerations in mind, one of the principal objects of this invention is to devise an arrangement and construction of parts and electric circuits whereby the greatest facility of movement of trains may be obtained with the greatest safety. 55

A further object of the invention is to devise a system for automatically controlling railroad trains, which will not only give the greatest facility and safety, but which will also satisfy the more important requirements and conditions found in the practical operation of railroads. 60

A further and more limited object of the invention is to devise a system for automatically controlling railway traffic in which the engineer or motorman of a train will be properly advised at all times whether or not he is operating his train with the highest speed consistent with safety. 65

A further specific object of the invention is to devise an arrangement and construction of parts and electric circuits for an automatic train control system in which a distinctive signal will be automatically displayed in the engineer's cab while and so long as the train is being operated in the direction opposite to the normal direction of traffic. 70

A further specific object of the invention is to devise an arrangement and construction of parts and electric circuits for an automatic train control system in which the engineer, after he has obeyed a caution signal and has brought his train to a safe speed, may proceed further by manipulating a certain device, which device will automatically extinguish the regular cab signals and render effective a distinctive signal to keep the engineer advised that he is proceeding without being under the protection of the automatic train control system, until the train has reached a point where the train control system may be made effective again to control the train without unnecessary delay, whereupon the distinctive signal is automatically nullified and the regular cab signals are automatically restored. 75

A further specific object of the invention is to devise a simple and reliable means for protecting certain relays used in the system embodying the invention from injury by an

excessive or continued flow of current, such as may occur under certain conditions more fully explained hereinafter.

The invention consists in the parts and in the arrangements and combinations of parts, together with the electric controlling circuits therefor, all of which are more fully set forth hereinafter.

In describing the invention in detail, reference is had to the accompanying drawing in which is illustrated the preferred physical embodiment of the invention, in which like reference characters refer to like parts in the several views, and in which

15 Figure 1 is a schematic view, in the nature of a wiring diagram, which shows diagrammatically the parts and electric circuits constituting one form of the invention, said parts being illustrated more with regard to 20 making their functions and operation clearly understood than with regard to their exact arrangement and construction.

Fig. 2 is a view, diagrammatic in its nature, showing some of the parts carried by the train, said view being in part a section taken on the line 2—2 in Fig. 3;

Fig. 3 is a plan view of some of the parts shown in Fig. 2;

30 Fig. 4 is a section taken substantially on the line 4—4 in Fig. 3; and

Fig. 5 is a section of certain parts shown in Fig. 2 and is taken substantially on the line 5—5 of said figure, certain parts being omitted and broken away.

35 Referring to the accompanying drawing, the numerals 1 and 2 designate a portion of the track rails of the ordinary railway track, and these track rails 1 and 2 are divided by insulating joints (not shown) in 40 the usual manner into electrically isolated blocks or sections, each of which is provided with a source of electric current, as a battery, and a track relay or similar device of suitable construction. Since this arrangement constitutes the well known normally 45 closed track circuit, and since the detail construction and operation of this track circuit is very familiar to those skilled in the art of railway signaling, it has been deemed 50 unnecessary to complicate the illustration of this invention by showing the parts above mentioned.

The train is shown diagrammatically in Fig. 1 as comprising a pair of wheels 3—3 connected by the usual axle 4, and a second pair of wheels 5—5 connected by the axle 6, said axles 4 and 6 being connected by bars 7 and 8 representing the frame and body of a vehicle or of the separate vehicles of a train. According to the preferred embodiment of the invention which is illustrated in the accompanying drawing, communication between the train and the track necessary for the operation of the cab sig-

nals and the speed control apparatus is obtained by the mechanical and electrical co-operation of a contact shoe or shoes carried by the train with ramps or contact rails located at intervals along the track, there being preferably one ramp associated with

70 each block or track circuit section. These ramps may be of any suitable construction

and consists in general of a metallic contacting portion extending for some distance parallel with the track rails and fixed in 75 any suitable way on supports of insulating material, only two of these ramps being shown in Fig. 1 and designated R and R¹.

Likewise, the contact shoes may be of any suitable construction, and for simplicity are shown diagrammatically in Fig. 1. The particular embodiment of the invention illustrated requires the use of two contact shoes on the train, or on each single locomotive or motor car equipped with the system, these two shoes being disposed on opposite sides of the vehicle or train; and since the construction of these shoes is the same, their parts have been given corresponding reference characters with the distinctive exponent "1" and added thereto, and a description of one will suffice for both.

The simplified form of contact shoe shown comprises an angle lever 9 journaled on a pin 10, fixed to the side bars 7 or 8 of the vehicle, so that this angle lever may oscillate back and forth in a vertical plane. The vertical arm of the angle lever 9 is provided with a suitable enlargement or foot at its lower end which is adapted to engage the ramps along the track as the train progresses; and the horizontal extending arm of the angle lever 9 is connected to a metallic rod 11, to which is fixed and insulated therefrom a number of contact disks or blocks 12, 13, 14 and 15, which are arranged in certain positions to establish electrical connection between suitable contact springs or fingers illustrated conventionally in Fig. 1 by arrows. The upper end of the rod 11 of each shoe has a right angle bend 16 which is arranged to make contact with suitable contact springs indicated by arrows. The contact shoes S and S¹ are shown in Fig. 1 in the normal position which they assume when they are not in engagement with the ramp, and are provided with suitable means (not shown) which restores these shoes to their normal position after they have been operated.

The mechanical cooperation of the contact shoes S and S¹ with the ramps R and R¹ is accomplished by making the end portions of these ramps inclined, so that the shoes ride gradually on these inclined portions and are swung to one direction or the other relatively to the vehicle, according to which shoe engages a ramp and according to the direction

in which the vehicle is traveling, all as explained hereinafter. The electrical cooperation of the contact shoes with the ramps is due to the electrical contact of these contact shoes with the metallic contacting portion of the ramps, during which a partial circuit on the vehicle is connected to a partial circuit including a source of current and associated with each ramp, so that electric energy may be transferred from the ramp to the vehicle, subject to proper control in accordance with traffic conditions, and may be utilized for governing the cab signals and speed control apparatus by means of certain relays. The partial circuits associated with the ramps along the railway track are controlled by the track relays of the blocks or track sections of that track, so that these partial circuits may be established in accordance to the traffic conditions. For a clear understanding of this invention, however, it is unnecessary to illustrate and describe in detail the trackway circuits whereby the partial circuits associated with the ramps are controlled according to traffic conditions; and for simplicity the contacts operated by the track relays of the blocks or track sections adjacent to the ramps R and R¹ illustrated in Fig. 1, are replaced by simple switches. In the embodiment of the invention illustrated, the source of current associated with each ramp is a transformer which has a primary 17 connected to a suitable source of alternating current, which in practice is the usual transmission line, and a secondary comprising two portions 18 and 19, one terminal of said secondary being connected by a conductor 20 to one of the track rails, as the track rail 2. The switch for controlling the partial circuits associated with the ramp R is designated 22; and when the switch 22 is in the position shown in Fig. 1, which corresponds to the condition existing when the block or track circuit section with which the ramp R is associated is not occupied, a difference of potential, equal to the voltage of the combined secondary portions 18 and 19, is established between the ramp R and the track rail 2 by a partial circuit which may be traced as follows: commencing at the track rail 2, conductor 20, secondary portions 18 and 19, conductor 21, switch 22 and conductor 23 to ramp R. When the switch 22 is moved to its other position, indicated by a dotted line, a difference of potential equal to the secondary portion 18 alone is established between the ramp R and the track rail 2 by a partial circuit which may be traced as follows: commencing at the track rail 2, conductor 20, secondary portion 18, conductors 24 and 25, switch 22, and conductor 23 to the ramp R. The ramp R¹ has only one partial circuit associated therewith, which is controlled by the switch 27, and

when this switch 27 is closed a difference of potential equal to the voltage of the secondary portion 18 is established between the track rail 2 and said ramp R¹ by a partial circuit which may be traced as follows: commencing at the track rail 2, conductor 20, secondary portion 18, conductors 24 and 26, switch 27 closed, and conductor 28 to the ramp R¹. The switches 22 and 27 have a still further position in which they disconnect the ramps R and R¹ entirely from the secondary portions 18 and 19, so that no difference of potential exists between said ramps and the track rail 2.

The significance of these partial circuits will be pointed out more fully hereinafter in the description of the operation; but it can be seen that by proper manipulation of the switch 22, three electrical conditions of the ramp R may be obtained, namely: first, a condition wherein a high difference of potential exists between this ramp and a track rail, this condition being conveniently termed high voltage applied to the ramp R; second, the condition wherein a low difference of potential exists between said ramp R and a track rail, this condition being conveniently termed low voltage applied to the ramp R; and third, the condition wherein no difference of potential exists between the ramp R and a track rail, this condition being conveniently termed no voltage applied to the ramp R. The ramp R¹, however, has only two electrical conditions, one in which low voltage is applied to said ramp, and the other in which no voltage is applied to said ramp.

According to an arrangement illustrated in Fig. 1, the normal direction of traffic is from left to right, as indicated by the arrow X; and according to this invention it is contemplated, although it is appreciated that such an arrangement is not compulsory, that the majority of the ramps will be like the ramp R and will be located on the righthand side of the railroad track as regards the normal direction of traffic; whereas the ramps R¹, located on the lefthand side of the railroad track, will occur only at certain points where it is desired to produce an immediate and absolute stop in a way which the motorman or engineer is powerless to prevent, such a place being, for instance at a point where there are converging tracks.

In order to properly govern the speed control apparatus on the train in accordance with the varying length of blocks and their varying physical characteristics, for the reasons explained more fully hereinafter, a selector mechanism, shown diagrammatically in Fig. 1 and designated generally L, is supported in the vehicle, preferably on an axle thereof, so as to extend transversely of said vehicle and the track. As shown,

this selector mechanism L comprises a base or frame plate 29 extending transversely of the vehicle and of the railroad track, in which are slidably mounted vertically movable plungers or tappets 30, 31, 32, 33 and 34, which have enlarged end portions or feet. The feet of these selector tappets are disposed a short distance above the ties or road bed of the railroad, with such clearance as may be desired, and are arranged to be struck by selector ramps having inclined end portions. These selector ramps (which are not shown) extend longitudinally of the railroad track and are positioned at different points between the track rails, so that each selector ramp engages only one of the selector tappets. Each of the selector tappets is spring-pressed downward by a compression spring 35 to the lower or normal position shown in Fig. 1; and after passing through the frame plate 29, said selector tappets pass through openings in a horizontally movable latch plate 36, said openings in said latch plate having one edge (shown as the right hand edge) beveled or undercut as clearly shown in Fig. 1. A tension spring 38 is connected between the base plate 29 and the latch plate 36 and tends to move said latch plate to the left, as viewed in Fig. 1. Each of the selector tappets 30, 31, 33 and 34 is provided with an integral projection or catch 37, the upper edge of which is beveled to conform to the beveled edge of the corresponding opening of the latch plate 36, and the lower edge of which forms a shoulder. The middle selector tappet 32 has its upper edge beveled to correspond to the opening in the latch plate 36 through which it passes, but is not provided with a shoulder as in the case of the other selector tappets. The upper ends of the selector tappets 30 and 34 are pivotally connected to the ends of a floating lever 40, and the ends of a similar floating lever 39 are pivotally connected to the upper ends of the tappets 31 and 33. Pivotally connected to the middle of the floating lever 39 is a vertical rod or plunger 41, which has fixed thereto and insulated therefrom a contact disk or block 42 arranged to make electrical contact with suitable contact springs or fingers illustrated diagrammatically as arrows. A similar rod or plunger 43 is pivotally connected to the floating lever 40 at its middle point, and this rod 43 carries three insulated contact disks 44, 45 and 46.

The cab signals and speed control apparatus are governed by a relay on the vehicle which is hereinafter termed the speed control relay and is designated SC. The speed control relay SC preferably comprises two separate windings 47 and 48 and is provided with armatures or contact fingers which are illustrated conventionally in the draw-

ing and are designated 49, 50, 51, 52 and 53. The speed control relay SC is in turn controlled by another relay, hereinafter termed the pick-up relay and designated P. The pick-up relay P is preferably designed so as to be operated only by alternating current; but since relays having this characteristic are well known in the art, it is unnecessary to illustrate and describe the construction of this pick-up relay in detail. The pick-up relay P is provided with two armatures or contact fingers 54 and 55, one of which, 54, controls the speed control relay SC, as explained hereinafter, and the other of which controls a protective resistance 56 in the manner explained hereinafter. The pick-up relay P is governed by a partial circuit terminating at the wheels of the vehicle and at one of its contact shoes in an operated position; and the pick-up relay P may be directly connected to the frame or wheels of the vehicle and to the contact shoe, but it is preferred to interpose a transformer T¹ in this partial circuit, so that any direct current finding its way into this partial circuit will not reach the pick-up relay P.

For the purpose of controlling the movement of the vehicle or train so that it may be brought to an absolute stop, there is provided an alternating current relay, hereinafter termed the stop relay and designated SR. This stop relay SR is also governed by a partial circuit terminating at the wheels of the vehicle and at the contact shoe on said vehicle in an operated position, and in the same way and for the same reason as explained hereinbefore in connection with the pick-up relay P, a shielding transformer T is preferably interposed in this partial circuit. The stop relay SR is provided with two armatures or contact fingers 57 and 58, one of these armatures, 58, being used to control or shunt a protective resistance 59 in the local circuit for said stop relay.

Another relay, hereinafter termed a "no-signal" relay and designated NS, is carried on the vehicle and is used to give a distinctive indication in the motorman's cab in case he is operating his train in the direction opposite to the normal direction of traffic, or has performed the special manipulation necessary to release his train from the dominance of the speed control apparatus, and further to perform other controlling functions. The no-signal relay NS is preferably provided with two separate windings 60 and 61, and is arranged to operate a number of armatures or contact fingers designated 62, 63, 64, 65 and 66.

According to this invention it is contemplated that the vehicle or train to which the system is applied, will be equipped with the ordinary and well known system of

pneumatic brakes, although other means for retarding the movement of the train or vehicle may be employed. This type of braking system is well known in the art, and to avoid complication has not been shown in detail; and for a clear understanding of this invention it is sufficient to point out that this braking system comprises a train pipe, a portion of which is illustrated in Fig. 1 and designated 67, and that the brakes are automatically applied by venting this train pipe, a suitable electrically operated valve being used for this purpose. This valve is designated generally as E and comprises a valve 68, which is urged or pressed to its open position by a spring 69, and is held in its closed position by the energization of the solenoid E.

The cab signal equipment on the train or vehicle has been illustrated diagrammatically and has been shown in duplicate in order to illustrate the application of the speed control system embodying this invention to a locomotive or motor car which is provided with a cab at each end. The cab signal comprises a special warning signal A, which is preferably an audible signal such as a whistle or the like; a proceed signal, which is shown as a green lamp G; a caution signal, which is shown as a yellow lamp Y; and a no-signal device, which is shown as a white lamp W. In addition to these signals there are in each cab two lamps 70 and 71, the function and purpose of which will be explained more fully hereinafter. Two lamps of different intensities for each of the above mentioned signals are preferably used in each cab so that the brightness of these signals may be changed according to whether or not the train is being operated in the day time or at night, or in a tunnel or subway. The above mentioned signals in each of the cabs are controlled by a suitable manually operated switch, designated generally U, which is arranged in position so as to be conveniently actuated by the motorman. This switch U serves the double purpose of enabling the motorman to cut-in or cut-out the cab signals in that particular cab, and to control the intensity of these signals as he desires. The cab signal cut-in and dimming switches U are illustrated in a simple way as comprising a series of contact blocks or pieces 72 which may be engaged by a long contact bar 73. A resistance 74 is preferably used in series with each of the cab signal lamps in order that low resistance lamps having strong filaments may be used. In each of the cabs is located a manually operable switch or circuit controlling key K by means of which the motorman is able under certain conditions to release his train from the dominance of the speed control apparatus, as explained more fully hereinafter.

Under some conditions in the practical operation of railroads there are occasions where two or more locomotives or motor cars, each equipped with the train control apparatus, are included in the same train, and it is desirable that the train control apparatus on these several locomotives or motor cars should in some respects be simultaneously controlled; and for this purpose there are shown a number of continuous conductors or bus lines 75, 76 and 77 extending between the several motor cars or locomotives included in the train. The bus line 75 affords a connection for simultaneously restoring the parts of the train control system on each of the motor cars or locomotives to their normal or idle condition when occasion requires; the bus line 76 affords a connection whereby the motorman may release his train from the dominance of the speed control apparatus on the several locomotives or motor cars in the train; and the bus line 77 affords a connection which enables the warning signal A in the cab which the motorman occupies to be operated by any one of the train control apparatus on the several motor cars or locomotives.

The essential parts of the speed control apparatus are shown diagrammatically in Figs. 2 to 5 inclusive and comprise in general a device for indicating the permissive speed for the vehicle at different points in its travel, a second device for indicating the actual speed of the vehicle at these points, and mechanism subjected to the joint control of said two devices for electrically governing the brakes of the vehicle by means of the electrically operated valve E, together with appliances for governing the operation of the several parts. The devices for indicating the permissive speed and the actual speed are connected to the axle of a pair of wheels of the vehicle, preferably to the axle of a pair of wheels which are neither braked nor driven, so that said devices are actuated in accordance with the rate of movement of the vehicle and the distance of its travel; and while this mechanical connection may be made in various ways, it is illustrated simply in the drawing as comprising a worm 78 secured to the axle 4 and meshing with a worm wheel 79 which is fixed to the lower end of a shaft 80 journaled in suitable supports 81 and 82 and held against endwise movement by collars 83 and 84 pinned thereto and disposed below and above the supports 81 and 82, respectively. The shaft 80 actuates the device for indicating the actual speed of the vehicle, and this device is shown as a speed indicator SI of the well known centrifugal type commonly used as a speed governor for engines.

The speed indicator SI is shown in a simplified form and comprises a block 85 pinned or otherwise securely fixed to the shaft 130

- 80 and a second block 86 which is mounted on said shaft 80 so as to slide lengthwise thereon; and interposed between these two blocks 85 and 86 is a cocompression coil spring 87. Pivotally connected at their ends to the blocks 85 and 86 are links 88, the adjacent ends of which are pivotally connected to weighted balls 89. The operating parts of the speed control apparatus are in practice supported in a suitable box or casing which protects said parts and also affords a means for supporting these various parts in the manner and in the relation necessary for their proper operation. To show the arrangement which is preferably adopted would, however, only serve to complicate the illustration, and there is shown for simplicity portions of a casing or frame, designated generally by the letter F, which affords a convenient means for supporting the operating parts. Journaled in bearings attached in any suitable way to the frame F is a shaft 90, hereinafter termed the speed-shaft, which has fixed thereto, as by a key, an arm 91 which extends to the speed indicator and is connected to the lower block 86 thereof by means of the usual collars and yoke. By reason of this construction it is apparent that as the speed of the vehicle changes and the speed of rotation of the shaft 80 correspondingly varies, the weighted balls 89 will be thrown outwardly by centrifugal force and will lift the lower block 86 against the opposition of the spring 87, so as to rock the arm 91 up or down in accordance with the variation of the speed of the vehicle, so that the speed-shaft 90 assumes different angular positions according to the actual speed of the vehicle existing at that instant.
- The device for indicating the permissive speed for the vehicle is shown as connected to the shaft 80 by means of a beveled gear 92 which is fixed to said shaft and which meshes with a mating beveled gear 93 fixed to one end of a shaft 94 journaled in suitable lugs or brackets shown integral with the frame F. Fixed to the other end of the shaft 94 is a worm 95 which meshes with a gear 96 journaled on a suitable bearing stud 97 secured to the frame F; and fixed to the gear 96 is a smaller gear 98 which meshes with a larger gear 99 journaled on a bearing stud 100 also secured to the frame F. In a similar way a small gear 101 is secured to the gear 99 and meshes with a larger gear 102 journaled on a bearing stud 103; and a small gear 104 is secured to the gear 102 and meshes with a larger gear 105 supported on a suitable bearing stud 106. It is apparent that the construction and arrangement of gears just described constitutes the well known system of reduction gearing. Journaled at one end on the bearing stud 106 is an arm 108, to which are fixed two pins 109 and 111; and journaled on said pins are two meshing gears 110 and 112, the gear 110 being also in mesh with a gear 107 fixed to the gear 105. The arm 108 is controlled by an electromagnet hereinafter termed the cam control magnet C, which comprises two coils 113 having their pole pieces connected at their lower ends by a yoke or strap 114 which is fastened by bolts to lugs shown integral with the frame F. The armature 116 of the cam control magnet C is guided by pins 115 secured in the pole pieces of the coils 113, and rigidly connected to the armature 116 is a rod 117 which extends downwardly through the yoke 114 and is pivotally connected to the outer end of the arm 108. A compression coil spring 118 encircles the rod 117 and bears at its lower end against the yoke 114 and at its upper end against a collar 119 pinned or otherwise suitably fastened to the rod 117.
- Supported in any suitable manner in the casing F is a shaft 120, hereinafter termed the cam-shaft, to which is pinned a comparatively large gear 121 which has a semi-circular portion cut out of its periphery, as indicated by the numeral 122; and the gear 121 is arranged in the same plane as the gears 112 and 110 so that the gear 112 may be moved into and out of mesh with the gear 121. It is apparent that when the arm 108 is in its upper position, as shown in Fig. 2, and when the gear 112 is in mesh with the gear 121, the cam-shaft 120 is directly connected to the axle 4 and is turned gradually exactly in accordance with the movement of the axle 4 and the wheels 3 secured thereto in such a way that the angular displacement of the shaft 120 from its initial position when the arm 108 was first raised represents the distance subsequently traveled by the vehicle.
- The speed-shaft 90 and the cam-shaft 120, which, as pointed out hereinbefore, assumes different positions in accordance with the actual speed of the vehicle and the distance traveled thereby, respectively, are preferably arranged to control a number of units, which for convenience may be termed block combinations; but since the construction of these units is the same in all respects except that the exact shape of the cams used varies slightly, only one of these block combinations has been shown in Figs. 2 to 5 inclusive, and a description of this one will suffice for all. Associated with each block combination are two cams 123 and 124 which are securely fastened, as by pins, to the cam-shaft 120. The shape of these cams is slightly different, as can be readily seen by comparing the cam 123 shown in Fig. 2 with the cam 124 in Fig. 4, and the reason for this difference in the shape of the cams will be explained more fully hereinafter.

Associated with each of these cams 123 and 124 is a circuit controlling device which is governed jointly by the corresponding cam and the speed-shaft 90; and these circuit controlling devices are arranged side by side as shown in Fig. 3 in the form of a unit and have some parts in common. The number of circuits controlled by the respective circuit controlling devices and the manner in which they are controlled is different, and makes it necessary to describe them separately.

Referring particularly to Figs. 2 and 3, there is a shelf or ledge H integral with the frame or casing F to which are secured blocks 125 of suitable insulating material; and fastened to these blocks are members 126 which support the contact fingers 127, 128 and 129, and which also act as binding posts. According to the construction shown, each of these contact fingers has a pair of ears 130 which are pivotally connected to the upper end of the corresponding member 126 so as to be capable of a slight rocking movement in a vertical plane; and arranged to press against one side of each of these contact fingers is a compression spring 131 secured to the corresponding member 126 in a manner which can be readily understood from the drawing.

Below the ledge H a single coil electro-magnet 132 is bolted to the frame F, and also secured to the frame F is a yoke of magnetic material comprising upper and lower arms 133 and 134 respectively, which are disposed respectively above and below the electro-magnet 132. The outer edge of the upper arm 133 is beveled to form a knife edge, and the armature 135 of the electro-magnet 132 rests against this knife edge and is held closely in contact therewith by means of a compression spring 137 which surrounds a pin 136 fixed at one end to said arm 133 (see Fig. 4) and which bears at one end against the outer face of said armature 135 and at its other end against a collar or washer on the pin 136, the outward movement of said washer being limited by a small pin extending transversely through the pin 136.

Riveted to the armature 135 of the electro-magnet 132 is an extension 138 which extends upwardly to a point above the ledge H about on a level with the upper ends of the contact fingers 127, 128, 129, and this extension 138 is connected to a yoke-shaped frame J comprising side portions 139, 140 and an end portion 141. The upper end of said extension 138 is journaled on a pin 144 riveted to the outer ends of the side portions 139, 140, sleeves 145 (see Fig. 3) being used to hold the extension 138 in proper position on said pin 144. A bolt 142 is anchored at one end to the frame F and extends through a hole in the end portion

141 of the frame 5; and interposed between the nut on said bolt 142 and said end portion 141 is a compression spring 143. The side portion 139 of the frame J carries three rollers 146 of insulating material which are journaled on pins riveted or otherwise secured to said side portion and which are spaced apart at such distances as to maintain the upper ends of the contact fingers 127, 128 and 129 spaced apart so as to be separated only a short distance, as shown in Fig. 2. Secured to the outer contact finger 127 is a roller 147 of insulating material which is arranged to bear against the edge of a contact sector 149 loosely mounted on a shaft or rod 148 fixed to the frame F. The contact sector 149 has a downwardly extending arm 150 which is connected to one end of a tension spring 151, the other end of which is anchored to the upper insulating block 125. A link 152 is pivotally connected at one end to the arm 150 and at its other end to the middle point of a floating lever 153. The floating lever 153 is provided with a roller 154 which is revolvably mounted on a pin fixed in the upper end of said floating lever and which presses against the edge of the cam 123; and the lower end of the floating lever 153 is journaled on a rod 155, (see Fig. 5) which is carried by two arms 156 (only one of which is shown) which are fastened by pins or other suitable means to the speed-shaft 90.

Referring to the circuit controlling device associated with the cam 124 and shown in Figs. 3 and 4, the contact fingers 157 and 158 controlled by this other cam 124 are similar in construction to those already described and are mounted in the same way upon the insulating block 125. Two rollers 159 of insulating material are secured to the side portion 140 of the yoke-shaped frame 5, and are arranged, as shown in Fig. 4, to bear against said contact fingers. The rollers 159 are so located that the contact fingers 157 and 158 will be separated when they bear against said rollers, and when these contact fingers are pressed together, as shown in Fig. 4, the roller 159 associated with the contact finger 158 is closer to said contact finger than the other roller 159 associated with the contact finger 157. The outer contact finger 157 carries a roller 160 of insulating material which bears against the outer edge of a contact sector 161, also journaled on the shaft 148, suitable sleeves 148¹ being disposed on shaft to space apart the contact sectors 149 and 161. A downwardly extending arm 162 integral with the contact sector 161 is connected by a tension spring 163 to the insulating block 125 in a manner similar to that already described in connection with the contact sector 149; and the arm 162 is connected by a link 164 to a floating lever 165

which carries a roller 166 at its upper end bearing against the edge of the cam 124 and which is journaled at its lower end on the rod 155.

- 5 The outer edge of the contact sector 149 is formed with two shoulders 167 and 168, and the outer edge of the contact sector 161 is formed with a single shoulder 169, the shoulders 167 and 168 being similarly disposed and both different from the shoulder 169, for the reasons and for the purpose hereinafter explained.

10 The cam-shaft 120 is provided with an appliance for restoring it to its initial position after it has been operated. This appliance (see Figs. 2 and 5) comprises an arm 170 journaled at its upper end on a pin or shaft 171 supported in lugs 172 integral with the frame F, and this arm 170 is formed 15 with a toothed sector at its lower end, which meshes with a pinion 173 keyed to the cam-shaft 170. Also journaled on the pin 171 are two blocks 174 and 175 which are held against endwise movement in one direction 20 by a small pin 176 extending transversely through the shaft 171; and the arm 170 has integral therewith a laterally extending foot or lug 177 which is arranged 25 to strike either of the blocks 174 or 175 as the arm 170 is rocked in one direction or the other. Extending loosely through each of the blocks 174 and 175 is a rod 178, one 30 end of which is fixed to a boss 179 integral with the frame F; and encircling each rod 35 178 is a compression coil spring 181, one end of which presses against the corresponding blocks 174 or 175, and the other end of which bears against a washer or collar 182 held in place on said rod 178 by 40 the small transverse pin 183.

45 *Operation.*—Before taking up in detail the operation of the different parts of the train control system embodying this invention and before tracing the different circuits involved in this operation, a brief statement of the operation in general will be given. As the vehicle or train equipped with the train control apparatus approaches a block or number of blocks of substantially 50 the same length and physical characteristics, the selector L is operated by selector ramps located along the track at this point in such a way as to energize the electro-magnet 132 of the block combination which is designed 55 to properly control the speed of the train through the block or blocks into which the train is about to enter. At about the same time that this selection of the cams to control the train is made, the first righthand 60 contact shoe of the train engages a ramp located on the righthand side of the track. If traffic conditions ahead of the train in question are such that this train 65 may proceed safely the electrical condition of this ramp is governed by the trackway

circuits so that the speed control apparatus on the vehicle is not set into operation, and except for the limitation upon the maximum speed which the train may attain at any time, as explained hereinafter, the train may proceed at unlimited speed, the motorman being advised of these conditions by the presence of a proceed signal in his cab. In case, however, traffic conditions ahead of the train in question are such that this train should 70 so control its speed as to come to a stop at the end of the block into which it is entering, the electrical condition of the ramp above mentioned is so governed by the trackway circuits that the proceed signal is changed 75 to a caution signal, and the speed control apparatus is set into operation. In general, the speed control apparatus operates to sound a warning signal as the train proceeds and has moved to such a point 80 and is traveling at such a speed that the brakes should be immediately applied in order to bring the train to a stop by the time it reaches the end of the block it then occupies, and then, in case this warning signal is disregarded, the speed control apparatus 85 automatically causes an application of the brakes.

90 Referring to Fig. 1, of the parts of the speed control apparatus shown in Figs. 2 to 5 inclusive are shown in a simplified form, and in Fig. 1 two block combinations M and N are shown together with the circuits controlling them and the circuits controlled 95 thereby. The operation of the system is conveniently divided into the operation of certain groups of its parts; and the different steps in the operation of each group together with the circuits involved in this 100 operation will now be set forth in detail.

105 To facilitate the tracing of the circuits involved in the operation of the train control system it is convenient to trace all of these circuits from one conductor 180, indicated by a double line, which is directly connected to one terminal of the battery B on the vehicle, to another conductor 190, indicated by a heavy line which is connected to the other terminal of said battery B, it being apparent that the different circuits are 110 completed through these conductors 180 and 190 regardless of the point at which the particular circuit in question is shown as connected to said conductors. For convenience the conductor 180 will be termed the local positive wire and the conductor 190 will be termed the common return wire. Also, in 115 describing the operation, occasion will be had to refer to circuits which have been previously traced in the preceding part of the description, and in order to avoid unnecessary repetition and yet enable each circuit referred to to be positively and easily identified, each of the circuits as it is traced 120 will be given a designating number, and will 125 130

be thereafter referred to by that number. For ready reference a table of these circuits with their numbers and functions will be given as follows:

	Circuit number	Function.	
5	1	Energizes the electromagnet 132 of the block combination N.	
10	2	Energizes the electromagnet 132 of the block combination M.	
15	3	Normally closed stick circuit for the speed control relay SC.	
20	4	Energizing circuit for the pick-up relay P when the speed control relay SC is energized and said relay is deenergized.	
25	5	Energizes the speed control relay SC when the armatures of the pick-up relay P are raised.	
30	6	Partial circuit on the vehicle for controlling the pick-up relay P when the shoe S is the righthand shoe.	
35	7	Complete circuit for controlling the pick-up relay P when the contact shoe S is the righthand contact shoe and engages a righthand ramp R to which high voltage is applied.	
40	8	Lights the green lamp G.	
45	9	Lights the yellow lamp Y.	
50	10	Energizes the cam control magnet C when the speed control relay SC is energized.	
55	11	Circuit for controlling the valve E, which is controlled by the contact shoes and by the speed control contact fingers.	
60	12	Circuit for controlling the valve E which is controlled by the speed control relay SC and by the speed control contact fingers.	
65	13	Circuit for controlling the valve E which is controlled by the stop relay SR and by the speed control contact fingers.	
70	14	Circuits for controlling the valve E when the no-signal relay NS is energized.	70
75	15	Gives the advance signal when the block combination N is effective.	
80	16	Gives the audible signal when the block combination N is effective.	
85	17	Energizing circuit for the relay NS controlled manually by the motorman.	
90	18	Stick circuit for the relay NS.	
95	19	Gives the no-signal indication by lighting the white lamp W.	
100	20	Energizes the cam control magnet C when the relay NS is energized.	
105	21	Energizing circuit for the stop relay SR when that relay is energized.	
110	22	Partial circuit on the vehicle for controlling the stop relay SR when the shoe S ¹ is the lefthand shoe.	
115	23	Partial circuit on the vehicle for controlling the stop relay SR when the shoe S is the lefthand shoe.	
120	24	Complete circuit for controlling the stop relay SR when the shoe S ¹ is the lefthand shoe and is in engagement with a lefthand ramp to which low voltage is applied.	70
125	25	Energizes the relay NS when the vehicle moves against traffic and the shoe S ¹ is the lefthand shoe.	75
130	26	Circuit for the track relay indicator lamp 70.	
135	27	Circuit for the contact shoe indicator lamp 71.	80

Operation of the selector.

The parts of the selector L are shown in Fig. 1 in the position which is preferably selected as corresponding to the block combination which will control the train under the worst conditions, that is, under the conditions of the shortest block found along the railroad with the steepest down grade. As shown in Fig. 1, all of the selector tappets are in their lower position when this selection of the block combination for the worst conditions is made; and when said selector tappets are in the lower position, a circuit for energizing the electromagnet 132 of the block combination N is established.

Circuit Number One.

Local positive wire 180, conductor 184, lower contact spring 185, contact block 42 in its lower position, conductor 186, contact block 44 in its lower position, conductor 187, electromagnet 132, conductors 188, 189 and 191 back to the common return wire 190.

The electromagnets 132 of the other block combinations are energized by actuating the selector tappets 30 and 34, inclusive, separately or in certain groups. When either of the outside selector tappets 30 or 34 is lifted, one end of the floating lever 40 is raised and its other end is held stationary by the other selector tappet which is not lifted, so that the rod 43 is moved to an intermediate position, in which the circuit for energizing the electromagnet 132 of one of the block combinations is closed. In the particular arrangement of circuits shown in Fig. 1, this movement of the rod 43 to its intermediate position, while the rod 41 remains in its lower position, closes the circuit for energizing the electromagnet 132 of the block combination M, said circuit being traced as follows:

Circuit Number Two.

Commencing at the local positive wire 180, conductor 184, contact block 42 in its lower position, conductor 186, contact block 130

44 in its intermediate position, conductor 192, electromagnet 132, and conductors 193 and 191 to the common return wire 190.

In case the outside selector tappets 30 and 34 are simultaneously lifted, both ends of the floating lever 40 are raised and it can be seen that this results in a movement of the rod 43 to its upper position, in which a circuit for energizing the electromagnet 132 of some other block combinations (not shown), is established. In a similar way the rod 41 may be operated to either an intermediate position or an upper position, depending upon whether the selector tappets 31 and 33 are lifted one at a time or simultaneously; and it can be seen that the selector L is capable of selectively controlling nine different sets of circuits.

When any one of the selector tappets 30, 31, 33 or 34 is raised, the catch 37 of that selector tappet cooperates with the beveled edge of the corresponding opening in the latch plate 36 and slides said latch plate to the right as shown in Fig. 1, against the opposition of the spring 38; but as soon as the selector tappet in question has reached its upper position, the catch 37 thereon clears the corresponding opening in the latch plate 36, whereupon said latch plate is pulled to the left by the spring 38, so that the upper edge of the opening through which the selector tappet in question passes, engages under the edge of the corresponding catch 37 and locks this selector tappet in its upper position. By reason of this construction, it can be seen that each of the selector tappets 30, 31, 33 and 34 after being lifted is locked in its upper position by the latch plate 36, and is held in its upper position until said latch plate is shifted. The shifting of the latch plate 36 to release any of the selector tappets which may be locked thereby in the upper position is accomplished by lifting the middle selector tappet 32; and when said middle selector tappet 32 is lifted, its beveled upper end cooperates with the beveled edge of the opening in the latch plate 36 through which it passes to shift said latch plate to the right far enough to release the catches 37 of any of the selector tappets which may be held in their upper position at this time. In the operation of the selector L under ordinary conditions the selector ramps for actuating the selector tappets are so positioned that the middle selector tappet 32 is first raised to unlock any of the selector tappets which may have been previously raised to obtain the selection of a particular block combination, and then one or more of the selector tappets 30, 31, 33 or 34, as may be necessary to obtain the new selection desired, are raised, and while these selector tappets are held in their upper position by the selector ramps with which they

are in contact, the middle selector tappet is permitted to assume its lower position, whereupon these selector tappets for the new selection are locked in their upper position. It should be noted that the operation of the selector L and the selection obtained thereby is the same when the vehicle travels in either direction, since the lifting of either of the selector tappets 30 or 34 or either of the selector tappets 31 or 33 produces exactly the same result.

The energization of the electromagnet 132 of a given block combination by the operation of the selector L places that block combination in condition to be effective to control the movement of the vehicle, while all of the other block combinations, which have their electromagnets 132 deenergized, are not in such condition as to be able to control the movement of the vehicle. Referring to Fig. 1 the block combination N is shown in condition to be effective to control the vehicle, while the block combination M is shown in its ineffective condition. Referring to Figs. 2 to 4, inclusive, it can be seen that if the electromagnet 132 is deenergized, the spring 143 will draw the yoke-shaped frame J to the right from the position shown in these figures, so as to rock the contact fingers 127, 128 and 129, all together and still separated from each other, to the right until the roller 147 carried by the outer contact finger 127 would not be engaged by the shoulders 167 and 168 on the edge of the contact sector 149 if said contact sector were rocked downward. In the case of the contact fingers 157 and 158, this movement of the frame J draws the contact finger 158 out of electrical contact with contact finger 157, and holds it out of contact therewith, so that the circuit controlled by these contact fingers is broken, regardless of the position of the shoulder 169 on the edge of the contact sector 161 with reference to roller 160. This position of the parts of the block combinations just described is shown in connection with the block combination M in Fig. 1, and it is apparent that all of the circuits controlled by different contact fingers of the block combination M are broken.

Operation of the speed control relay SC and the pick-up relay P.

As indicated hereinbefore the control of the cab signals and the speed control apparatus depends upon the electrical condition of the ramp on the righthand side of the railroad track, and this control is produced when the contact shoe on the righthand side of the train engages this ramp. The proceed signal, the caution signal and the speed control apparatus are governed by the speed control relay SC by means of certain electric circuits explained in detail hereinafter; and the speed control relay SC in turn is con-

trolled by the righthand contact shoe on the vehicle and also by the pick-up relay P. Under normal conditions, that is, when the proceed signal is displayed in the motor-man's cab, and when the speed control apparatus is not effective to control the movement of the train, except as regards its maximum speed, the speed control relay SC is energized and its armatures are in the upper position, as shown in Fig. 1. The speed control relay SC is energized under normal conditions as just stated by a circuit which may be traced as follows:

Circuit Number Three.

15 Commencing at the local positive wire 180, conductor 194, contact block 15 of the righthand shoe S in its lower position, conductor 195, contact block 15¹ of the lefthand contact shoe S¹ in its lower position, conductors 196 and 197, armature 63 of the no-signal relay NS in its lower position, conductor 198, armature 49 of the speed control relay SC in its upper position, conductor 199, winding 48 of the relay SC, and conductors 200 and 201 to the common return wire 190.

The circuit last traced is interrupted when the contact shoe S engages the ramp R and the vehicle is headed in the direction shown in Fig. 1 and is traveling in the normal direction of traffic indicated by the arrow X, since this engagement of the shoe S of the ramp R results in the angle lever 9 being rocked to the left, as viewed in Fig. 1, so that the rod 11 is raised and the contact block 15 moved out of electrical contact with the conductors 194 and 195. This circuit would also be broken if the vehicle were headed in the opposite direction to that shown in Fig. 1, so that the shoe S¹, shown as the lefthand shoe, were to engage a righthand ramp R, since in this case the angle lever 9¹ of the shoe S¹ would be rocked to the right, as viewed in Fig. 1, and would raise the rod 11¹ and move the block 15¹ out of electrical contact with the conductors 195 and 196. In other words, the engagement of the righthand shoe on the vehicle with a righthand ramp when the vehicle is traveling in the normal direction of traffic, breaks the circuit which normally energizes the speed control relay SC, so that unless some other means for maintaining the speed control relay SC energized is set into operation, the armatures of said relay will drop to their lower position, thereby changing the proceed signal in the cab to a caution signal, and also setting the speed control apparatus into operation in the manner hereinafter explained. It should be noted that the armature 49 of the speed control relay SC is included in the circuit Number Three above traced for normally energizing said relay, so that when the armature 49 of this relay drops, this circuit is incapable of reenergizing

ing said relay. In this way after the speed control relay SC is deenergized by the engagement of a contact shoe with a ramp, when the contact shoe leaves engagement with the ramp, the speed control relay is not 70 reenergized.

Having described the manner in which the speed control SC is so controlled that it tends to give a caution signal and set the speed control apparatus into operation whenever a righthand contact shoe on a vehicle engages a righthand ramp, it is next in order to consider the operation of the pick-up relay P by means of which the speed control relay SC may be maintained energized or may be allowed to become deenergized, according to whether it is permissible for the vehicle to proceed at a speed as great as the physical characteristics of the stretch of track over which it has been passing will permit, or the vehicle should proceed cautiously. The pick-up relay P is included in a circuit comprising the secondary of the transformer T¹, a preventive resistance 202 and a protective resistance 56, there being provided for each of these resistances a low resistance shunt. When the pick-up relay P and the speed control relay SC are in the normal position, that is, the relay P is deenergized and the relay SC is energized, 75 the circuit for the relay P may be traced as follows:

Circuit Number Four.

100 Commencing at one terminal of the secondary of the transformer T¹, conductor 203, relay P, conductors 204, 205 and 206, armature 55 of the relay P in its lower position, conductor 207, armature 50 of the relay SC in its upper position, and conductor 208 105 back to the other terminal of said secondary. As soon as the armature 55 of the pick-up relay P is raised, the low resistance shunt for the protective resistance 56 is broken, and current flowing through said relay P 110 must flow through the resistance 56. The resistance 56 is so proportioned that it limits the flow of the current in the relay P to an amount which will not injure the relay P in case of an excessive flow of current or if 115 current continues for some time through the relay P, as for instance, in case the train should stop for some time with a contact shoe on a ramp. In case the speed control relay SC is deenergized at the time the current is first induced in the secondary of the transformer T¹, the low resistance shunt for the preventive resistance 202 is broken at the armature 50 of the relay SC, and under 120 these conditions, the current induced in the 125 secondary of the transformer T¹ must be of higher voltage in order to send current through the pick-up relay P sufficient to lift its armatures. This arrangement allows the 130 armatures of the pick-up relay P to be selec-

tively controlled by different voltages, as explained more fully hereinafter.

When the armature 54 of the pick-up relay P is raised, the winding 47 of the speed control relay SC is energized by a circuit which may be traced as follows:

Circuit Number Five.

Commencing at the local positive wire 180, conductors 209 and 210, armature 54 of the relay P in its upper position, conductors 211 and 211¹ winding 47, and conductors 212 and 201 to the common return wire 190.

In this way the armatures of the speed control relay SC are held in their upper position or are raised to their upper position whenever the armature 54 of the pick-up relay P is raised to its upper position. The current is supplied to the pick-up relay P from the secondary of the transformer T¹, and the primary of said transformer is included in a partial circuit which terminates at the wheels of the vehicle and at the right-hand contact shoe of the vehicle when that contact shoe engages a righthand ramp. When the vehicle is headed in the direction shown in Fig. 1, and is traveling in the normal direction of traffic indicated by the arrow X, the shoe S is the righthand shoe; and when this shoe engages the righthand ramp R, the angle lever 9 is swung backward to the left as viewed in Fig. 1, so that the rod 11 is raised. Under these conditions the partial circuit including the primary of the transformer T¹ may be traced as follows:

Circuit Number Six.

Commencing at the contacting portion of the shoe S, through the angle lever 9, rod 11, angle bend 16, conductors 213 and 214, primary of the transformer T¹, and conductors 216 and 217 to the axle 6 of the vehicle.

It may happen that the vehicle, shown in Fig. 1, may be headed in the opposite direction and may at the same time be traveling in the normal direction of traffic indicated by the arrow X; and in this case the shoe S¹ would become the righthand shoe and would be in position to engage the ramp R. When the shoe S¹ becomes the righthand shoe and when it engages the ramp R, the angle lever 9¹ of said shoe is swung to the right, as viewed in Fig. 1, so that the rod 11¹ is raised and the angle bend 16¹ thereof is brought into contact with the conductor 218, thereby electrically connecting the contact shoe S¹ by means of conductors 218, 219, and 214 to one terminal of the primary of the transformer T¹. From this it is apparent that the shoes S and S¹ perform exactly the same function when either is the righthand shoe of the vehicle.

As explained hereinbefore, there is associated with the righthand ramp R two partial circuits including the portion 18

alone or the portions 18 and 19 together of the secondary of the transformer associated with that ramp; and when the contact shoe S is in engagement with the ramp R, the partial circuit on the vehicle including the primary of the transformer T¹ and one of the partial circuits associated with the ramp R are connected so that current may flow from the transformer to the ramp R through the primary of the transformer T¹ on the vehicle. When the switch 22 is in the position shown in Fig. 1, that is when there is high voltage applied to the ramp R, the complete circuit for the primary of the transformer T¹ may be traced as follows:

Circuit Number Seven.

Commencing at the ramp R, angle lever 9 of the shoe S, rod 11, angle bend 16, conductors 213, and 214, primary of the transformer T¹, conductors 216 and 217 to the axle 6, hence by the wheel 5 to the track rail 2, conductor 20, secondary portions 18 and 19, conductor 21, switch 22 and conductor 23, back to the ramp R. The circuit corresponding to this last traced circuit which is established when the shoe S¹ is the righthand shoe may be easily traced by analogy to the circuit just traced and need not be set forth in detail.

The voltage of the combined secondary portions 18 and 19 of the ramp transformer is so selected that sufficient current will be induced in the secondary of the transformer T¹ to energize the pick-up relay P, even with the preventive resistance 202 in series with said relay, sufficiently to raise the armatures of said relay; or, in other words, when high voltage is applied to the ramp R, the armatures of the pick-up relay P will be raised and will in turn cause the armatures of the speed control relay SC to be raised, regardless of whether or not said armatures of the speed control relay are in their upper or lower position at the time. The voltage of the secondary portion 18 alone of the ramp transformer, however, is selected so that sufficient current will be induced in the secondary of the transformer T¹ to energize the pick-up relay P sufficiently to raise its armatures when the preventive resistance 202 is shunted by the armature 50 of the speed control relay SC, but so that when the preventive resistance 202 is included in series with the pick-up relay P, the armatures of said pick-up relay P will not be raised. In other words, if the vehicle approaches the ramp R with the armatures of its speed control relay SC in their upper position, high voltage applied to the ramp R followed by low voltage will serve to keep the armatures of the speed control relay in their upper position; and in case the train approaches the ramp R with the armatures of its speed control relay in their lower

position, if high voltage is applied to the ramp R, said armatures of the speed control relay SC will be raised, and will be held in their raised position even if the high voltage applied to the ramp R is followed by low voltage. Obviously, if the switch 22 is moved to the position to disconnect the ramp R from the secondary of the transformer associated therewith, no current will be induced in the secondary of the transformer T¹ and the armatures of the pick-up relay P will either drop to their lower position, or will remain in their lower position as the case may be.

From the foregoing it can be seen that the armatures of the speed control relay may be restored to their upper position and held in that position while the train passes the ramp R; or the armatures of said speed control relay may be restored to their upper position and then caused to drop again to their lower position while the train is passing the ramp R; or the armatures of said speed control relay, if in their upper position, may be held there while the train passes the ramp R; or said armatures, if they are in their lower position, may be caused to remain there while the train is passing the ramp R. This control of the speed control relay is accomplished by changing the voltage applied to the ramp R and this voltage is in practice automatically controlled by the track relays of the certain track sections in advance of the ramp R; but since these trackway circuits form no part of the present invention, they are not shown, but are arranged for the proper control of the system embodying this invention so that when a train approaches the ramp R, high voltage will be applied to said ramp, providing the track section next in advance of the ramp R and protected thereby is not occupied; so that this high voltage will be changed to low voltage providing the second track section in advance of the ramp R is not occupied; so that this high voltage will be changed to no voltage if said second track section in advance of said ramp is occupied; and so that low voltage will be applied to the ramp R initially if the track section next in advance of said ramp and protected thereby is occupied.

As explained hereinbefore, a bus line 75 is provided for electrically connecting the several motor cars or locomotives equipped with the train control system which are included in the same train, and this bus line 75 on each of said motor cars or locomotives is connected by the conductor 220 to the conductor 211 which is connected at times to the local positive wire 180 when the pick-up relay P is energized, so that when the pick-up relay P on any one of said

motor cars or locomotives is energized as hereinbefore described, current is transmitted from the local positive wire 180 along the bus line 75 to the winding 47 of the speed control relays SC on the several motor cars or locomotives, and thence by conductors 212, 201, common return wire 190, and conductor 300 to the wheels and axles of said motor cars or locomotives to the track rail 2 which forms a common return. In other words, the pick-up relays P on the several motor cars or locomotives in a train may be energized simultaneously. This arrangement facilitates the movement of traffic for the reason that when a train including a number of motor cars or locomotives, is being controlled by the speed control apparatus on the several motor cars or locomotives, and approaches a righthand ramp, all of the relays P on the train may be simultaneously energized to simultaneously restore the parts of the speed control apparatus on the several motor cars or locomotives to the initial or idle condition; and consequently the train as a whole is released from the speed control apparatus as soon as the first motor car or locomotive reaches the righthand ramp R having high voltage thereon, so that the movement of the train as a whole is not delayed as it would otherwise be until the last locomotive or motor car of that train reaches such a ramp.

Referring to the controlling functions provided by the speed control relay, the armature 51 of said relay controls the proceed and caution indications. When the armature 51 is in its upper position the green lamp G indicating proceed is lighted by current flowing in a circuit which may be traced as follows:

Circuit Number Eight.

Commencing at the local positive wire 180, conductors 221 and 222, armature 64 of the no-signal relay NS in its lower position, conductors 223 and 224, armature 51 of the speed control relay in its upper position, conductor 225, conductor 226, and thence through the resistance 74 of the green lamp G in either cab, through the cab signal cut-in and dimming switch U in the cab occupied by the motorman, and conductor 227 to the common return wire 190.

In this connection it is noted that all of the cab signal lamps are controlled by the cab signal cut-in and dimming switches U, and that the circuits for these cab signals through said switches U are so easily traced that detailed explanation is unnecessary.

The yellow lamp Y, indicating caution, is lighted by current flowing in a circuit established when the armature 51 of the

speed control relay SC is in its lower position, said circuit being traced as follows:

Circuit Number Nine.

- 5 Commencing at the local positive wire 180, conductors 221 and 222, armature 64 of the no-signal relay NS in its lower position, conductors 223 and 224, armature 51 of the speed control relay SC in its lower position, conductors 228 and 229 to the common conductor 230 for the yellow lamps Y, and thence in the same way as explained hereinbefore through the cab signal cut-in and dimming switch U to the common re-
15 turn wire 190.

The armature 53 of the speed control relay SC controls the cam control magnet C, and when said armature is in its upper position, the cam control magnet C is energized by a circuit which may be traced as follows:

Circuit Number Ten.

- 25 Commencing at the local positive wire 180, conductors 209, 230 and 231, armature 53 in its upper position, conductors 232 and 233, cam control magnet C, and conductors 234, 189 and 191 back to the common return wire 190.

30 *Control of the brakes.*

The electrically operated valve E is subjected to the control of a number of devices and is governed by a number of controlling circuits. The first controlling circuit for the valve E may be traced as follows:

Circuit Number Eleven.

- 40 Commencing at the common return wire 190, conductor 235, valve E, conductors 236, 237 and 238, contact fingers 157 and 158 of the block combination N, conductors 239, 240 and 241, and thence either along conductor 242, contact block 12¹ of the shoe S¹ and conductor 243 to the local positive wire 180, or conductor 244, contact block 12 of the shoe S and conductor 246, to the local positive wire 180.

Regarding this controlling circuit Number Eleven for the valve E, it should be noted that said circuit is not interrupted unless both contact shoes are operated by engaging corresponding ramps, since the operation of the shoe S still leaves the circuit closed at the shoe S¹, and vice versa. It should also be noted that the separation of the contact fingers 157 and 158 of the block combination N interrupts the above traced controlling circuit Number Eleven for the electrically operated valve E, regardless of the position of the contact shoes. Another controlling circuit for the electrically operated valve E is substantially the same as the circuit just traced except that the con-

tact fingers 157 and 158 of the block combination M are included in this circuit, the connection being made by conductors 254 and 255 in an obvious manner.

Another controlling circuit for the electrically operated valve E may be traced as follows:

Circuit Number Twelve.

Commencing at the common return wire 190, conductor 235, valve E, conductors 236, 237 and 238, contact fingers 157 and 158 of the block combination N, conductors 239, 240, 247 and 248, armature 52 of the speed control relay SC in its upper position, and conductors 230 and 209 to the local positive wire 180.

Regarding this last traced circuit, it should be noted that the branch thereof controlled by the armature 52 of the speed control relay SC is in multiple with the branch of the preceding circuit Number Eleven controlled by the contact shoes S and S¹, so that if the circuit Number Eleven is interrupted at the contact shoes S and S¹, nevertheless the valve E is energized by current flowing in the circuit Number Twelve. In the same way, there is a further circuit, having a portion thereof in multiple with the branches of the two preceding circuits Numbers Eleven and Twelve; and this further circuit may be traced as follows:

Circuit Number Thirteen.

Commencing at the common return wire 190, conductor 235, valve E, conductors 236, 237 and 238, contact fingers 157 and 158 of the block combination N, conductors 239, 240, 247, 249 and 250, armature 57 of the stop relay SR in its upper position, and conductor 251 to the local positive wire 180.

It should be noted that each of the three controlling circuits Numbers Eleven, Twelve and Thirteen for the electrically operated valve E above traced is interrupted whenever the contact fingers 157 and 158 of the block combination N are separated. There is, however, a shunt for these contact fingers controlled by the armature 66 of the no-signal relay NS, so that, when the armature 66 of this no-signal relay is in its upper position, current may flow:

Circuit Number Fourteen.

From the common return wire 190, along conductor 235, through the valve E, conductors 236 and 252, armature 66 of the relay NS in its upper position, conductor 253, and thence along conductor 250, through the armature 57, of the stop relay SR, or along conductors 249 and 248 through the armature 52 of the speed control relay SC, or

along conductors 249, 247 and 241 through the contact blocks 12 and 12¹ of the shoes S and S¹, to the local positive wire 180, without passing through the contact fingers 157 and 158.

Advance and audible signals.

In connection with the system embodying this invention, a signal is given in the motorman's cab whenever his train is running as fast as the block combination in effect will permit, when the train is being run under the proceed signal. In other words, this signal which is termed the advance signal, tells the motorman when his train is traveling at a speed nearly as great as safety will permit. The advance signal in the particular arrangement shown in Fig. 1 is given by lighting the yellow lamp Y at the same time that the green lamp G is lighted, the indication for the advance signal being given by the simultaneous showing of green and yellow lights. The advance signal is controlled by the cam 123 of the block combination effective at the time, and remembering that the block combination N is effective when the parts are in the position shown in Fig. 1, the circuit for lighting the yellow lamp Y at the same time that the green lamp G is lighted, may be traced as follows:

Circuit Number Fifteen.

Commencing at the local positive wire 180, conductors 221 and 222, armature 64 of the no-signal relay NS in its lower position, conductors 223, 256 and 257, contact fingers 128 and 127, conductors 258, 259 and 229 to the common wire for the yellow lamps Y, and thence through the cab signal cut-in and dimming switch U and conductor 227 to the return wire 190. A similar circuit which can be easily traced by analogy to the circuit just traced is established when the block combination M or any other block combination in the speed control apparatus is effective, and when the speed of the vehicle is nearly as great as the maximum permissible speed for the vehicle at that time.

The warning or audible signal A is controlled by the cam 123 of the block combination which is effective at the time, and when the block combination N is effective the circuit for the audible signal A may be traced as follows:

Circuit Number Sixteen.

Commencing at the local positive wire 180, conductors 221 and 222, armature 64 of the no-signal relay NS in its lower position, conductors 223, 256 and 257, contact fingers 128 and 129, conductors 262, 263 and 264 to the common wire 265 for the audible signals A in each cab of the vehicle and thence

through the cab signal cut-in and dimming switch U to the common wire 190. The common wire 265 of the audible signals A on each vehicle is connected by conductors 264 and 266 to the audible signal bus line 77; and by reason of this arrangement of circuits the audible signal in either cab of any one of the motor cars or locomotives included in the same train may be sounded by the operation of the speed control apparatus on any one of the several motor cars or locomotives in said train, thereby enabling the motorman to be in some other cab except the first cab of the first motor car of the train if necessary, and also obtaining the benefit of the simultaneous operation of the different speed control apparatus on the several motor cars or locomotives.

Shape of the cams.

85

In determining the proper manner in which to automatically control the speed of railroad trains so that maximum facility with the greatest safety may be obtained, it is necessary to consider the factors which affect the braking distance of railroad trains, that is, the distance in which a railroad train may be brought to a stop by its brakes. In the first place, the distance required to bring a train to a stop by its brakes depends upon the kind of braking equipment, also upon the speed of the train at the time the brakes are first applied, upon the grade of the track over which the vehicle travels while being stopped, the curves in this track and other factors dependent upon the special physical characteristics of this stretch of track over which the train passes while being stopped. It is possible, as is clearly understood by those skilled in the art of braking trains, to determine what is known as the braking curve for a train, taking into consideration a certain kind of braking equipment and a given stretch of track, this braking curve being a speed-distance curve which represents for each point in the travel of the train with its brakes applied the speed at that point at which the train will be running. In other words, this braking curve for a train shows how fast the train can be moving at any given point in its travel and yet be brought to a stop by its brakes before another certain point is reached.

The shape of the cams 123 and 124 is determined from the braking curve of the train on which these cams are mounted with regard to a certain grade, curve, or the like factors which affect this braking curve, and in some cases it is desirable to have cams of particular shapes for different lengths of blocks having like physical characteristics, since it may be desirable, in order to obtain the best facility and movement of trains over the track, to have a number of blocks of different lengths but of the same physical

100

105

110

115

120

125

130

characteristics. In the particular kind of cam illustrated, the lengths of the radii of said cam represent different speeds, and the angular displacement of said cam from its initial position represents the distance traveled by the train after the cam commences to move. In effect, each cam represents a predetermined functional relation between the speed of the train and the distance traveled by said train, this functional relation being based upon the braking curve for said train and upon a stretch of track of certain physical characteristics. Referring to the cam 124, this cam is based directly upon the braking curve of the train, while the cam 123 is derived from said braking curve but represents a curve which is a certain fixed time in advance of the braking curve at all speeds. The effective action of the cams 123 and 124 takes place along the line of movement of their respective followers, namely, the rollers 154 and 166, this line of movement being determined by the lower end of the speed-arm 156 and the rod 155. In this connection it should be clearly understood that the cams 123 and 124 of the different block combinations are of different shapes, and also will be of different shapes for different types of trains having different braking equipments, and that while the shape of these cams as shown in the drawing illustrates in a general way the shape of a cam which may be used in practice, no attempt has been made to show these cams precisely.

35   *Automatic Speed Control.*

Having set forth the different circuits involved in the operation of the speed control apparatus, the sequence of operation of the several parts when a train approaches the entrance to a block next in the rear of another block which is occupied by a second train may be set forth in detail. As the train under consideration approaches the ramp R, high voltage will be applied to said ramp; and consequently when the righthand contact shoe on said train engages said ramp R the pickup relay P will be energized by circuit Number Seven and will energize the winding 47 of the speed control relay SC by circuit Number Five so as to raise the armatures of said speed control relay to the upper position, if they are not already there. With the armatures of the speed control relay in the upper position the green lamp, indicating proceed, is lighted by circuit Number Eight and circuit Number Ten for energizing the cam control magnet C is closed. Referring to Fig. 2, it can be seen that when the cam control magnet C is energized, the arm 108 is moved to its lower position, thereby drawing the gear 111 out of mesh with the gear 121, so that the cam-shaft 120 is free to be placed in its initial position, as shown in Fig. 2, by the restoring mecha-

nism, if it is not already there. As the train progresses further, the voltage on the ramp R is automatically changed by the operation of the trackway circuits to no-voltage; and consequently the pickup relay P being entirely deprived of current, drops its armatures and interrupts the circuit Number Five for energizing the winding 47 of the speed control relay SC, whereupon the armatures of said speed control relay drop, since the contact shoe of the vehicle is still in engagement with the ramp R so that circuit Number Three for energizing the winding 48 of said speed control relay is interrupted. When the armature 51 of the speed control relay SC drops, the circuit Number Eight for the green lamp G is interrupted and the circuit Number Nine for the yellow lamp Y is established, thereby changing the proceed indication in the motorman's cab to a caution indication. When the armature 53 of the speed control relay SC drops, it interrupts circuit Number Ten for energizing the cam control magnet C; and referring to Fig. 2, it can be seen that when the cam control magnet C is deenergized, the arm 108 is moved upward by the spring 118, so that the gear 112 is in mesh with the gear 121. In this way the cam-shaft 120 is directly connected to the axle 4 of the vehicle by means of the intermediate gearing and commences to turn, in one direction or the other, depending upon the direction of movement of the vehicle, gradually and exactly in accordance with the distance traveled by the vehicle. This movement of the cam-shaft 120 causes a corresponding movement of the several cams of the different block combinations connected to said shaft, and the cams 123 and 124 of these block combinations cooperate with one end of the corresponding floating lever 153 to indicate the permissive speed for the vehicle at the different points in its travel.

As pointed out hereinbefore, the actual speed of the train is indicated by the speed indicator SI, and the angular displacement of the speed-shaft 90 and the speed-arm 156 represents different speeds. The speed-arm 156 and the rod 155 are shown in Fig. 2 in the position corresponding to zero speed; and the lower end of said speed-arm and the rod 155 are moved toward the left, as viewed in Fig. 2, as the speed of the train increases. If the cam 123 remains stationary in its initial position as shown in Fig. 2, as the speed of the train increases, the lower end of the floating lever 153 will be moved to the left, as viewed in Fig. 2, and since the upper end of this floating lever remains stationary, the link 152 connected to its middle point is correspondingly moved to the left, thereby rocking the contact sector 149 clockwise against the opposition of the spring 151. The parts are so proportioned

that when the train attains a speed which is the highest speed which it may safely maintain when proceeding under a proceed signal, the contact sector 149 is moved to the point 5 where the shoulder 168 in the edge thereof engages the roller 147 and shifts the contact spring 127 over into contact with the contact spring 128. The contact springs 127 and 128 when moved into contact close the 10 circuit Number Fifteen for the yellow lamp Y; and if at this time the green lamp G is also lighted, the motorman is given an indication, herein termed the advance signal, which informs him that his train is traveling 15 as fast as is properly allowable.

This condition just described in which the advance signal would be displayed would probably exist when the train under consideration passes the ramp R and when the 20 cam control magnet C is first deenergized. Referring to Fig. 2, it can be seen that when the cam 123 commences to turn it causes the upper end of the floating lever 153 to move to the left and assume different positions as 25 the train progresses according to the permissive speed for the train at the different points in its travel. The other or lower end of the floating lever 153, however, takes different positions in accordance with the actual speed of the train; and it can be seen that, as the cam 123 is rotated and the upper end of the floating lever 153 is moved to the left, in order to prevent the link 152 attached to the middle point of said floating lever 30 from being moved further to the left, the lower end of the floating lever must move as far to the right as the upper end of said floating lever is moved by the cam 123 to the left. In case the motorman properly 35 controls the speed of his train, the movement of the lower end of the floating lever 153 to the right, to compensate for the movement of the upper end of said floating lever to the left, will occur and no further movement 40 of the link 152 and the contact sector 149 is produced; but if the motorman should disregard the caution signal, or should by reason of carelessness, negligence or incompetency fail to properly control the speed 45 of his train, the contact sector 149 will be rocked still further clockwise and the shoulder 167 in the edge thereof will engage the roller 147 and cause a movement of the contact fingers 127 and 128 together to the right 50 until the contact finger 128 makes electrical contact with the contact finger 129, whereupon the circuit Number Sixteen for sounding the audible signal A is closed. The sounding of the audible signal A advises 55 the motorman that he is not properly controlling the speed of his train and that the speed of his train is approaching dangerously close to the highest speed which it is possible for the train to have at that particular point in order to bring the train 60

to a stop by its brakes by the time it reaches the end of the block. Ordinarily the motorman will quickly observe the audible signal A and will cause a manual application of the brakes which will serve to reduce the speed 70 of the train to a safe speed. In some cases, depending upon the particular shape of the cam 123, this immediate application of the brakes by the motorman will result in the speed of the vehicle being reduced at a 75 greater rate than is required by the curve which the cam 123 represents; and under these conditions the reduction of the speed of the vehicle will cause the lower end of the floating lever 153 to move to the right farther and faster than the upper end of said floating lever is moved to the left by the cam 123 during the same interval of time, so 80 that the spring 151 may draw the link 152 to the right and rock the contact sector 149 85 counterclockwise far enough to bring the shoulder 167 out of engagement with the roller 147, thereby permitting the springs 131 to force the contact fingers 127 and 128, which still remain in contact, far enough to 90 the left so that the contact fingers 128 and 129 are separated and the circuit Number Sixteen for the audible signal A interrupted. In this way the motorman is advised that he has been successful in retarding the speed 95 of his train to the required restricted speed; but in case the speed of the train should again exceed the required restricted speed, as for instance, if the motorman should release his brakes too soon, the audible signal 100 A will again be sounded in the same way as described. From the foregoing it can be seen that the speed control apparatus provides a warning signal which will be sounded at any time during the travel of the train 105 through a block whenever the permissive speed is nearly reached, and which will persist until obeyed.

During this movement of the cam-shaft 120 the cam 124 is also turned; and if the 110 motorman disregards the audible signal A, this cam 124 will move the upper end of the floating lever 165 to the left to such a point that, with the lower end of said floating lever in the position corresponding to the speed 115 of the train at that instant, the link 164 is moved so far to the left and the contact sector 161 rocked clockwise so far that the shoulder 169 in the edge thereof is brought opposite to the roller 160, thereby permitting the spring 131 to force the contact finger 157 away from and out of contact with the contact finger 158. The separation of the contact fingers 157 and 158 interrupts 120 each of the circuits Numbers Eleven, Twelve and Thirteen which control the electrically operated valve E; and when this valve E is deenergized the spring 69 opens the valve 68 and vents the train pipe 67 so as to cause 125 an automatic application of the brakes. 130

- This automatic application of the brakes may be either what is commonly termed a service application, or may be an emergency application, depending upon the construction of the valve E and the rapidity with which the train pipe is vented, all as will be clearly understood by those skilled in the art of braking trains. If desired, a suitable recorder or counter may be applied to the valve 5 E to register the number of automatic applications which have occurred; but since the application of a recorder or counter to such a use is well known in the art, no further explanation is necessary.
- 10 As pointed out hereinbefore, the shape of the cam 123, which controls the advance signal and the audible signal, while it is derived from the same braking curve as the shape of the cam 124, is specifically different from the shape of the cam 124. The reason for this is that a certain interval of 15 time after the sounding of the audible signal A and before the automatic application of the brakes should be allowed for the motorman to shut off the power and produce a 20 manual application of the brakes; and this interval of time is preferably made the same regardless of the speed at which the train is traveling at that time. The distance which 25 a train will travel in a given time varies with the speed of the train at that time, and hence it is apparent that the audible signal A should be sounded a different amount, as regards distance traveled by 30 the vehicle, in advance of the automatic application of the brakes for different speeds. In other words, while the cam 123 is intended 35 to cause the sounding of the audible signal A a certain fixed time in advance of the automatic application of the brakes by the cam 124, the shapes of these cams are different because they are displaced in accordance with the distance traveled by the vehicle 40 and because the distance traveled by the vehicle during this certain fixed time will vary 45 according to its speed.

Maximum speed limitation.

The speed control apparatus described is 50 also capable of operating in a way to cause the sounding of the audible signal A and a subsequent automatic application of the brakes whenever the speed of the train exceeds a predetermined maximum speed, this 55 predetermined maximum speed being determined by the block combination which is effective at the time. Referring to Figs. 2, 3 and 4 and assuming that a block combination shown therein is effective, it can 60 be seen that even though the cam 123 remains stationary in its initial position, shown in Fig. 2, the speed arm 156 cannot be moved to the left, corresponding to higher 65 speeds, more than a certain distance without pulling the link 152 so far to the left as to rock the contact sector 149 through an angle sufficiently great to bring the shoulder 167 opposite to the roller 147 and cause the closing of the contact fingers 128 and 129, thereby closing circuit Number Sixteen and 70 sounding the audible signal. Likewise, although the cam 124 remains stationary in the position shown in Fig. 4, the speed arm 156 cannot be moved to the left more than 75 a certain distance without rocking the contact sector 161 far enough to bring the shoulder 169 opposite the roller 160, thereby permitting the contact fingers 157 and 158 to separate and open the circuits Numbers Eleven, Twelve and Thirteen for the electrically operated valve E. In this way a 80 warning signal is sounded whenever the speed of the vehicle exceeds a predetermined speed and the brakes are subsequently automatically applied if the speed is increased 85 still further.

The parts may be so arranged and proportioned that this predetermined maximum speed may be made the same for each block combination or each block combination may 90 be given a particular speed. In addition to preventing a train from attaining an excessive speed at any time which may be dangerous, this arrangement for imposing a limitation upon the maximum speed assures that the speed of the train can never exceed a speed such that the cams are not effective to adequately control the speed of 95 the train.

Automatic release.

Assume that the train has been controlled in the manner just described, either automatically or manually by the motorman aided by the warning signal, and assume that this train approaches the entrance to a block which was formerly occupied by another train, and further assume that this other train has now left said block and has entirely entered the second block in advance. Under these conditions it is apparent that the first-mentioned or following train may 105 properly accelerate since there is one full block interval between the two trains; or, in other words, it is permissible to release the first train from the dominance of its speed control apparatus and recommence the cycle of operation of this apparatus. This is accomplished by temporarily reenergizing the speed control relay SC, and this 110 result is accomplished by temporarily picking up the armatures of the pick-up relay P. As explained hereinbefore, the trackway circuits for controlling the ramp R are so arranged that high voltage will be on said ramps, providing the next block immediately in advance thereof and protected thereby is not occupied, and this is the condition which exists under the particular circumstances assumed; and, as explained hereinbefore, this 115 120 125 130

high voltage on the ramp R energizes the pick-up relay P by circuit Number Seven sufficiently to raise its armatures, and the raising of the armature 54 of said relay energizes the winding 47 of the speed control relay SC by circuit Number Five, so that the armatures of that relay are raised. As soon as the armature 53 of the speed control relay SC reaches its upper position the circuit Number Ten for energizing the cam control magnet C is established; and referring to Fig. 2, it can be seen that the energization of said cam control magnet moves the arm 108 downward and brings the gear 112 out of mesh with the gear 121. During the movement of the cam-shaft 120 as the train traveled through the preceding block, the pinion 173 secured to said cam-shaft rocked the arm 170 in one direction or the other, depending upon the direction of rotation of the cam-shaft 120, thereby resulting in the compression of one or the other of the springs 178. Consequently, when the gear 112 is moved out of mesh with the gear 121, the cam-shaft 120 is free to be turned by the arm 170 and is restored to the initial position as shown in Fig. 2. The temporary energization of the speed control relay SC breaks circuit Number Nine and extinguishes the yellow lamp Y and closes circuit Number Eight to light the green lamp G for an instant, and this serves to advise the motorman that the speed control apparatus has been reset. After the resetting operation, as the train progresses further, the voltage on the ramp R is cut off by reason of the train ahead; and the pick-up relay P and the speed control relay SC are deenergized, so that the cycle of operation of the speed control apparatus is again commenced. At this time the speed of the train is very low due to the action of the speed control apparatus while the train was passing through the preceding block; and consequently it is possible for the train to accelerate while traveling through the greater portion of the next block it has just entered before it attains a speed which is nearly as great as the permissive speed. In this connection it should be noted that by reason of the release bus line 75 the speed control apparatus on the several motor cars or locomotives in the train are simultaneously released, so that the acceleration of the train is permitted without delay. From the foregoing it is apparent that, when two trains are following one another, the following train, while it is at all times properly protected, is not unnecessarily delayed.

When the speed control apparatus on the train or vehicle is set into operation and the vehicle is compelled to reduce its speed as it travels through a block, the arrangement may be such, depending upon the shape

given to the cams 123 and 124, that the vehicle may be compelled to come to a complete stop at the end of the block, or may be compelled to reduce its speed only to a predetermined low speed, such as, for instance, five miles per hour; but it is contemplated according to this invention that this latter arrangement will be employed. If, at the time the vehicle has reached the end of a block, the next block in advance is still occupied, the type of trackway circuits used with the system will be so arranged, as explained hereinbefore, that only low voltage will be applied to the ramp R at the entrance to this next block. This low voltage is not sufficient to pick up the armatures of the pick-up relay P, so that the parts of the speed control apparatus are not restored to their normal or idle condition, and consequently, if the vehicle proceeds into this next block, it must do so at the predetermined low speed. Obviously, if the vehicle proceeds at this predetermined low speed, the cam-shaft 120 will continue to be turned as the vehicle proceeds, and the cut-away portion 122 is provided in the edge of the gear 121 so that this further movement of the cam-shaft will not bind or injure the parts.

95

Manual release.

Practical operating conditions, however, require that some provision be made to enable a motorman to release his train from the dominance of the speed control apparatus after the train has been compelled to reduce its speed in accordance with the control of said speed control apparatus. For example, suppose that a train approaching the entrance to a certain block is compelled to reduce its speed and that when this train reaches the entrance to said block it finds that, according to the electrical condition of the ramp guarding said block, said block is occupied by another train. It may be said that ordinarily better facility of train movement is obtained if the following train under the circumstances just stated stays at the ramp guarding the entrance to said block until the other train leaves that block; but it may well happen that special conditions make it desirable, or in fact even necessary, that said following train should be able to enter that block which is indicated as being occupied. In the system embodying this invention, this result is obtained by the construction and arrangement of parts comprising the manual release key K, the manual release bus line 76, and the no-signal relay NS, together with its controlling circuits and the circuits controlled thereby. The manual release key K is preferably located in the motorman's cab so that it can be conveniently operated by him, but said key is preferably guarded in some suitable

100

105

110

115

120

125

130

way so that it cannot be operated accidentally. When the motorman presses the manual release key K in the cab which he occupies, a connection is made between the 5 local positive wire 180 on that car and the manual release bus line 76, this connection comprising conductor 295, key K closed, and conductors 296 and 297. On each motor car 10 or locomotive included in the train which is equipped with the speed control apparatus, a connection is made between the manual release bus line 76 and the winding 60 of the no-signal relay NS on that motor car or locomotive, a pair of contacts 277 15 being interposed in this connection and being operated by the speed indicator on that motorcar or locomotive in any suitable manner (not shown) so that these two contacts are not closed unless the speed of the train 20 is below a predetermined speed, such as, for instance, five miles per hour.

Assuming that the speed of the train is below said predetermined speed, when the motorman closes his manual release key K, a 25 number of multiple circuits, one for each locomotive or motorcar included in the train, are established, the circuit and the electrical connections for the motorcar shown in Fig. 1 being traced as follows:

30 *Circuit Number Seventeen.*

Commencing at the local positive wire 180, conductor 295, manual release key K, conductors 296 and 297, manual release bus line 35 76, conductors 276, contacts 277, conductor 278, winding 60 of the no-signal relay NS, and conductors 279 and 280 to the common return wire 190. The common return wire 190 is connected by conductor 300 to the 40 frame of the vehicle, so that the track rails act as a common return for these several multiple circuits.

Since the speed control apparatus is in operation at this time, the speed control relay 45 SC is deenergized and its armatures are in the lower position; and consequently as soon as the no-signal relay NS is energized, a maintaining or stick circuit therefor is established as follows:

50 *Circuit Number Eighteen.*

Commencing at the local positive wire 180, conductors 209, 230 and 231, armature 53 of the speed control relay in its lower position, 55 conductor 284, armature 62 of the relay NS in its upper position, conductors 285 and 286, winding 61 of the relay NS, and conductors 287 and 280 to the common return wire 190.

60 When the no-signal relay NS is energized, its armature 64 is lifted and interrupts circuits Numbers Eight, Nine, Fifteen and Sixteen, which control the green and yellow lamps, the advance signal and the audible 65 signal A, respectively, so that these cab sig-

nals are rendered incapable of acting. The armature 64 of the relay NS in its upper position closes a circuit which lights the white lamp W, which circuit may be traced as follows:

70

Circuit Number Nineteen.

Commencing at the local positive wire 180, conductors 221 and 222, armature 64 of the relay NS in its upper position, conductor 75 281, common wire 282 of the white lamps W, thence through the cab signal cut-in and dimming switch U in the cab occupied by the motorman to the common return wire 190.

When the armature 65 of the relay NS is 80 raised, it closes a circuit for energizing the cam control magnet C, which circuit may be traced as follows:

80

Circuit Number Twenty.

85

Commencing at the local positive wire 180, conductor 221, armature 65 of the relay NS in its upper position, conductors 283 and 233, cam control magnet C and conductors 234, 90 189 and 191 to the common return wire 190.

From the foregoing it can be seen that the motorman by operating the manual release key K may energize the cam control magnet C and restore the parts of the speed control apparatus to the normal position independently of the speed control relay SC; but in order to do so it is necessary that the speed of the train should be less than a predetermined speed, that is, the train must practically be at a stop; and in so doing the cab 100 signals, comprising the proceed signal, the caution signal, advance signal and the audible signal, which usually guide the motorman, are rendered ineffective, and a distinctive signal consisting of the white lamp W is displayed in the motorman's cab, so that it constantly reminds him that he is proceeding into an occupied block and that he must proceed with great caution prepared to stop within vision.

105

110

Absolute stop.

115

In the practical operation of railroads there are occasions where it is desirable to bring the train to an absolute stop, as for example, at places where there are converging or intersecting tracks, since it is apparent that at such places it should not be possible for a train, even if it is traveling at a very low speed, to proceed along a certain track which converges with or intersects another track over which another train has been given the right of way. The switches and signals at such places where there are converging or intersecting tracks are usually controlled by an interlocking machine, which, as is well understood by those skilled in the art of railway signaling, is so constructed and arranged as to prevent conflicting routes for trains being set up; but 125 130

in accordance with the principles of automatically controlling the movement of trains which this invention is designed to satisfy, it is desirable to provide means in addition to the speed control apparatus so that obedience to the signals controlled by the interlocking machine is compelled. For this reason it is desirable to provide an arrangement and construction of parts such that a train may automatically be brought to an absolute stop at an interlocked signal; but in this connection it should also be observed that it is necessary to arrange these parts so that the train is permitted to proceed at certain times, subject to control of its speed control apparatus, when the interlocked signal indicates proceed. In other words, at an interlocked signal it is necessary to make provision for two types of control, first, speed control in the same manner as at other points along the railroad, and second, for an absolute stop. According to the system embodying this invention these two types of control are obtained by placing at an interlocked signal a lefthand ramp R^1 and a righthand ramp R ; which are so located with reference to the signal that the train will have a righthand contact shoe thereon in engagement with a righthand ramp R when this train pulls up to said signal, and said train will have both its righthand contact shoe and its lefthand contact shoe in engagement with the righthand and lefthand ramps in case the train proceeds beyond the signal. Also, for reasons more fully explained hereinafter, the lefthand ramp R^1 is made shorter than the righthand ramp R , so that the lefthand contact shoe of the train will leave engagement with the lefthand ramp R^1 before the righthand contact shoe of said train leaves engagement with the righthand ramp R . Whether or not the train should be brought to an absolute stop or be allowed to proceed, subject to the control of its speed control apparatus, is determined by the voltages applied to said righthand and lefthand ramps, and this is accomplished by interposing in the controlling circuits of these ramps certain circuit controlling devices which are governed by the interlocking machine either directly or in conjunction with the corresponding interlocked signal. Not only is it necessary to make provision for bringing the train to an absolute stop at the interlocked signal, but when traffic conditions are such that a train should be stopped at said signal, it is necessary to control the voltage applied to the ramp or ramps in the rear of that signal in such a manner that the motorman on the train will be advised by the caution signal that said interlocked signal is set against him and the speed control apparatus on that train will be set into operation. This latter control is also obtained by including in the controlling circuits for the ramp or ramps in the rear of each interlocked signal suitable circuit controlling devices which are governed by the interlocking machine. By reason of this last mentioned control of the ramp or ramps in the rear of any interlocked signal, it will be readily understood, in view of the description hereinbefore given of the operation of the speed control apparatus, that the train by the time it reaches the interlocked signal will necessarily, either by reason of the action of the motorman or because of the automatic operation of the speed control apparatus, be traveling at a very low speed determined by the speed control apparatus.

Assume that a train which has had its speed so controlled approaches an interlocked signal set at stop. Under normal operating conditions the train will pull up at the signal and will have the righthand contact shoe in engagement with the righthand ramp at this signal. The armatures of the speed control relay SC will be in the lower position at this time, and since the interlocked signal is set at stop, either low voltage or no-voltage will be supplied to the ramp R , so that the armatures of the pick-up relay P will remain in their lower position, and likewise the armatures of the speed control relay SC . When traffic conditions have changed and are such that the train in question may proceed, the towerman performs the usual manipulation of the levers of the interlocking machine so as to clear the interlocked signal and simultaneously apply high voltage to the righthand ramp R and low voltage to the lefthand ramp R^1 . The application of the high voltage to the righthand ramp R energizes the pick-up relay P , which in turn energizes the speed control relay SC , which, as explained hereinbefore, restores the parts of the speed control apparatus to their normal or initial condition, so as to permit the train to proceed. Following the restoration of the parts of the speed control apparatus to their normal position, the voltage on the ramp R is determined by the traffic conditions in the blocks in advance, and will be controlled by the trackway circuits in the same way as in ordinary block territory so as to continue the proceed indication or to give a caution indication and set the speed control apparatus into operation again according to whether there is another train in the second block in advance. As the train moves by the interlocked signal, the lefthand shoe S^1 engages the lefthand ramp R^1 , the righthand shoe S being at the same time in engagement with the right hand ramp R . In other words, both of the contact shoes on the train are operated, the rod 11 in the case of the righthand contact shoe S being lifted, and the rod 11¹ in the case of the lefthand

contact shoe S^1 being pulled downward. The simultaneous movement of the rods 11 and 11¹ interrupts the circuit Number Eleven hereinbefore traced for the electrically operated valve E; but under the conditions assumed, low voltage is on the lefthand ramp R^1 and this serves to prevent an automatic application of the brakes by energizing the stop relay SR and closing circuit 10 Number Thirteen for the valve E. The controlling circuit for the stop relay SR includes the secondary of the transformer T and a protective resistance 59, there being a low resistance shunt for said protective 15 resistance controlled by the armature 58 of said stop relay. When the stop relay SR is deenergized the circuit therefor may be traced as follows:

20 *Circuit Number Twenty-one.*

Commencing at one terminal of the secondary of the transformer T, conductor 271, relay SR, conductors 274 and 273, armature 58 of said relay in its lower position and conductor 272 to the other terminal of said secondary.

As soon as the stop relay SR is energized and its armature 58 is raised, the low resistance shunt comprising conductors 272 and 273 around the protective resistance 59 is broken, so that current flowing through the coils of said relay must also flow through said resistance. The purpose of the resistance 59 is to prevent injury and overheating 35 of the stop relay SR under the conditions where a voltage higher than normal will be applied to the stop relay transformer T. The primary of the stop relay transformer T is included in a partial circuit terminating at the wheels of the vehicle and at a lefthand contact shoe on said vehicle in its operated position. When the shoe S^1 is the lefthand contact shoe, as shown in Fig. 1, this partial circuit for the primary of the 40 transformer T may be traced as follows:

45 *Circuit Number Twenty-two.*

Commencing at the shoe S^1 , rod 11¹ moved downward, angle bend 16¹, conductors 268 and 269, primary of the transformer T, and conductors 270 and 217 to the axle 6.

When the shoe S, which is shown in Fig. 1 as the righthand shoe, becomes the lefthand shoe, as would be the case if the vehicle shown in Fig. 1 were headed in the opposite direction, the partial circuit including the primary of the transformer T may be traced as follows:

50 *Circuit Number Twenty-three.*

Commencing at the contact shoe S, rod 11 moved downward, angle bend 16, conductors 275, 269, primary of the transformer T, and conductors 270 and 217 to the axle 6.

When the lefthand contact shoe of a train is in engagement with a lefthand ramp, as the ramp R^1 , the partial circuit including the primary of the transformer T terminating at that lefthand contact shoe, is 70 connected to the partial circuit associated with that lefthand ramp, so that electrical energy may be transmitted from the transformer associated with that ramp to the transformer T and thence to the stop relay 75 SR. To illustrate, referring to Fig. 1, when the contact shoe S^1 engages the ramp R^1 , the switch 27 being closed, current is supplied to the primary of the transformer T from the secondary portion 18 of the ramp 80 transformer along a circuit which may be traced as follows:

85 *Circuit Number Twenty-four.*

Commencing at the ramp R^1 , angle lever 9¹ of the shoe S^1 , angle bend 16¹ of rod 11¹ moved to its lower position, conductors 268, 269, primary of the transformer T, conductors 270 and 217, to the axle 6, and thence by the wheels 5 to the track rail 2, conductor 20, secondary portion 18, conductors 24 and 26, switch 27 and conductor 28 back to the ramp R^1 .

90 The circuit corresponding to the last traced circuit which is established in case the shoe S shown in Fig. 1 becomes the lefthand shoe, is substantially the same and may be easily traced without further explanation.

95 From the foregoing it can be seen that, regardless of the direction in which the vehicle is headed, the lefthand contact shoe thereon by engaging a lefthand ramp R^1 to which low voltage is applied, will energize the stop relay SR, and when the armature 57 of said stop relay is in its upper position, the circuit Number Thirteen is closed so that the valve E is maintained energized independently of circuit Number Eleven which is broken at the contact shoes. In this way, to permit a train to proceed past an interlocked signal indicating proceed, it is only necessary to apply low voltage to the lefthand ramp at that signal, while the voltage applied to the righthand ramp at that signal is controlled by the trackway 100 circuits in the same way as it would be controlled in ordinary block territory.

105 To explain the operation of the system to obtain the absolute stop, assume that a train which has had its speed control apparatus set into operation approaches the two ramps R and R^1 at an interlocking signal set at stop, there being either low or no voltage on the righthand ramp and no voltage on the lefthand ramp. Under the conditions 110 assumed the armatures of the speed control relay SC will be in their lower position; and in case the motorman is incapacitated or carelessly attempts to pass the interlocked signal while it indicates stop, as soon as the 115

120

125

130

- lefthand contact shoe engages the lefthand ramp, an automatic application of the brakes will result, since of the circuits for energizing the valve E, circuit Number 5 Eleven is broken at the contact shoes, circuit Number Twelve is broken at the armature 52 of the speed control relay, and circuit Number Thirteen is broken at the armature 57 of the stop relay SR, this latter circuit being broken by reason of the fact that the stop relay SR is not energized. In view of the number of things which must happen in order to obtain an automatic application of the brakes at an interlocked signal, it is difficult for this to occur accidentally, although at the same time the arrangement and construction of parts is such that when conditions are such that it is proper to cause this automatic application of the brakes, this number of things will surely happen and the automatic application of the brakes will surely result.

Running into unsignaled territory.

- It may happen that only part of a railroad is provided with ramps and the track-way circuits for operating the train control system, and when the train is traveling over a part of such a railroad which is not so equipped as to control the movement of this train, it is desirable to render the cab signals inactive, so as not to confuse or mislead the motorman, and by means of some distinctive signal constantly warn the motorman that he is running through unsignaled territory and must do so with great caution and strictly in accordance with his orders and the regulations of the road. This result is accomplished according to the system embodying this invention by automatically energizing the no-signal relay NS when a train passes from signaled territory into unsignaled territory and as pointed out hereinbefore, the energization of the relay NS interrupts the circuits Numbers Eight, Nine, Fifteen and Sixteen for the green and yellow lamps, the advance signal and the audible signal A, and closes the circuit Number Nineteen for the white lamp W, and circuit Number Twenty for the cam control magnet C. Referring to the way in which the relay NS is automatically energized when a train enters unsignaled territory, assume that the train is headed in the direction shown in Fig. 1 and is traveling in the direction indicated by the arrow X. The shoe S¹ is then the lefthand shoe, and if this shoe S¹ is operated by engagement with a lefthand ramp, while the righthand shoe S remains in its normal position, a circuit for energizing the winding 61 of the relay NS is established as follows:

Circuit Number Twenty-five.

Commencing at the local positive wire

180, conductor 288, contact block 13 of the shoe S, conductor 289, contact block 14¹ of the shoe S¹ in its lower position, conductors 290, 291 and 286, winding 61 of the relay NS, and conductors 287 and 280 to 50 the common return wire 190.

A similar circuit is established in case the shoe S is the lefthand shoe and the shoe S¹ is the righthand shoe, this circuit being in part as follows: Commencing at the local 75 positive wire 180, conductor 292, contact block 14 in its lower position, conductor 293, contact block 13¹ in its normal position, and conductor 294 to the conductor 291, and thence through the winding 61 of the relay 80 NS in the same way as just described.

The no-signal relay NS, after being energized is maintained energized by its stick circuit Number Eighteen controlled by the speed control relay SC; but since this relay 85 SC may be energized at the time the train runs into unsignaled territory, it is necessary, in order to assure the making of said stick circuit Number Eighteen, to cause the deenergization of said relay SC and this is 90 accomplished when the armature 63 of the relay NS is raised.

In view of this arrangement of controlling circuits, when it is desired to render inoperative the usual cab signals, and light the white lamp W, it is only necessary to place a ramp on the lefthand side of the railroad track, which will be engaged by the lefthand shoe of the train as it enters unsignaled territory. When a train passes from unsignaled territory back into signaled territory, the usual cab signals will not be restored and the white lamp W will not be extinguished until the speed control relay SC has been energized by reason of the fact that until the armature 53 of said speed control relay is raised, the no-signal relay NS will be maintained energized by its stick circuit Number Eighteen, with the effect upon the usual cab signals and the white lamp W as pointed out hereinbefore. In other words, the train in passing from unsignaled territory into signaled territory, will not be taken from the control of the motorman and placed under the control of the speed control apparatus until one of the righthand shoes on said train engages a righthand ramp having high voltage applied thereto, which means that the speed control apparatus is not rendered effective until there is at least one unoccupied block in advance of the train. When the train reaches such a ramp, the pick-up relay P is energized by circuit Number Four, and the speed control relay SC is in turn energized by circuit Number Five in the same way as hereinbefore explained; and when the armature 53 of the relay SC is raised, the stick circuit Number Eighteen for the relay NS is broken, whereupon the several 100 105 110 115 120 125 130

armatures of the relay NS return to their lower position and restore the cab signals and place the parts in their normal position.

5 *Running against the normal direction of traffic.*

Ordinarily it may be said that practical operating conditions of railroads are satisfied if the speed control apparatus is made effective only when the train is traveling in the normal direction of traffic, movement against the normal direction of traffic being in most cases made under special orders and regulations, so that speed control for against traffic movements may be dispensed with; but it is necessary to make suitable provision whereby the speed control apparatus will not be set into operation when a train 20 is making a movement against the normal direction of traffic, because the electrical condition of the ramps which this train encounters is such as to tend to stop the train, for the reason that the train itself causes 25 an operation of the trackway circuits such as to produce an electrical condition of these ramps the same as it is desired to produce in order to properly protect trains in the normal direction of traffic. It is also desirable to make provision whereby the usual 30 cab signals will be rendered inoperative when a train makes a movement against the normal direction of traffic and to display before the motorman a distinctive signal 35 which constantly tells him that he is making a movement in which he is not protected by signals and the speed control apparatus. These two results are obtained by automatically energizing the no-signal relay NS 40 as soon as a train commences a movement against the normal direction of traffic. As pointed out hereinbefore, the ramps, except at interlocked signals, are located on the righthand side of the track with reference 45 to the normal direction of traffic; and it is apparent that these ramps will be lefthand ramps for a train moving against the normal direction of traffic. Consequently, as soon as a train commences a movement 50 against the normal direction of traffic and passes a ramp, this ramp being a lefthand ramp as regards the direction of movement of the train, causes the automatic energization of the no-signal relay NS in the same 55 way as hereinbefore explained by closing circuit Number Twenty-five. The no-signal relay NS is maintained energized and its stick circuit Number Twenty-two controlled by the speed control relay SC in the same 60 way as explained hereinbefore; but since a train may commence a movement against the normal direction of traffic when the speed control relay SC is energized, it is necessary, in order to insure the making of the 65 stick circuit Number Eighteen, to interrupt

the circuit Number Three which normally maintains said relay SC energized, and this is accomplished by the raising of the armature 63 of the relay NS. As stated hereinbefore, there is a lefthand ramp R¹ at each 70 interlocked signal as well as a righthand ramp R, and in order to prevent the relay NS from being energized when the vehicle passes these two ramps, it is necessary to make the lefthand ramp R¹ shorter than the 75 righthand ramp R, so that the lefthand contact shoe of the vehicle will leave engagement with the lefthand ramp R¹ before the righthand contact shoe leaves engagement with its righthand ramp; and when 80 the lengths of said ramps are so proportioned, the circuit Number Twenty-five for energizing the relay NS is not broken at the contact block 13 of the righthand shoe S until the lefthand shoe S¹ has been 85 restored to its normal position and has opened the normally open break in said circuit at the contact spring 14¹ of said lefthand shoe.

The energization of the relay NS renders 90 the usual cab signals ineffective and causes a white light to be displayed in the motorman's cab in the same way as explained hereinbefore, so that the motorman is constantly reminded that his train is traveling against 95 the normal direction of traffic, and so that there is no reason for him to be confused or deceived by any of the regular cab signals. The armature 65 of the relay NS, when it is raised, closes the circuit Number Twenty 100 which energizes the cam control magnet C, so that the parts of the speed control apparatus are restored to the normal position and are held in this normal position. The armature 66 of the relay NS when raised closes 105 a shunt for the speed control contact fingers 157 and 158 of each of the block combinations, this shunt in the case of the block combination N in Fig. 1 comprises conductors 238, 237 and 252, armature 66 in its upper position and conductors 253, 249, 247, 240 and 239, so that circuit Number Fourteen 110 is established. The speed control contact fingers 157 and 158 of the other block combinations are also shunted, as will be readily apparent; and by reason of this shunt established by said armature 66, the separation of any one of the speed control contact fingers 157 and 158 will not interrupt the circuits Numbers Eleven, Twelve and Thirteen 115 for the brake controlling valve E, and these speed control contact fingers are thereby rendered incapable of imposing any limitation upon the maximum speed at which the train may run. It is desirable to so prevent 120 the operation of the valve E by the speed control contact fingers 157 and 158 for the reason that the maximum speed limitation, which would be imposed by these contact fingers effective to control said valve, would 125 not be correct for a train traveling against 130

the normal direction of traffic, because the operation of the selector L, by the selector ramps associated with each block, when the train moves against the normal direction of traffic, is such as to cause a limitation upon the maximum speed which is different from what it should be. In other words, the selector L, when a train moves against the normal direction of traffic, is operated to select 10 a certain block combination which corresponds to the block through which the train has already passed at that time, and this block combination may or may not correspond to the block into which the train is 15 about to enter.

If the train which has been traveling in the direction opposite to the normal direction of traffic reverses the direction of its movement and commences to travel again in 20 the normal direction of traffic, the relay NS is automatically deenergized as soon as this train passes a ramp to which high voltage is applied, since this ramp will be a righthand ramp as regards the new direction of the 25 train, and since high voltage is applied thereto, will energize the pick-up relay P sufficiently to raise its armatures, and the armatures of the speed control relay SC, being raised in turn, break the stick circuit Number 30 Eighteen for the relay NS. In this way, as soon as the train commences to move in the normal direction of traffic and reaches a point where there is one unoccupied block ahead of it, the train is automatically placed again under the control of the speed control 35 apparatus and the cab signals are restored.

Track relay indicator.

In order that the motorman in his cab may 40 be able to determine whether or not the track relays of the several blocks over which his train passes have properly operated, a lamp 70 is arranged in the motorman's cab so that voltage applied to the ramp of the corresponding block will be applied to said lamp. When the shoe S is the righthand shoe and 45 is in engagement with a righthand ramp R, to which high voltage is applied, the circuit for the lamp 70 may be traced as follows:

Circuit Number Twenty-six.

Commencing at the ramp R, shoe S, rod 50 11, angle bend 16, conductors 213, 219 and 298 to the common wire 299 for the lamps 70, thence through the cab signal cut-in and dimming switch U in the cab occupied by the motorman, thence along conductor 227 to the common return wire 190, along conductor 300 to the axle 4, thence by the wheels to the track rail 2, conductor 20, secondary portions 18 and 19, conductor 21, switch 22, and conductor 23, back to the ramp R.

In case the shoe S¹ is the righthand shoe of the vehicle, this shoe is connected by

conductors 218 and 298 to the common wire 65 299 for the lamp 70, when said shoe is raised by engagement with the righthand ramp and the complete circuit established through the lamp 70 may be easily traced by analogy with the circuit already traced. 70 As pointed out hereinbefore, the trackway circuits which control the electrical condition of the ramps R are so arranged that when a train approaches an unoccupied block, high voltage will be applied to the 75 ramp corresponding to that block, and this high voltage will change either to low voltage or to no voltage depending on whether or not the second block in advance is occupied, when the train actually enters the 80 block and shunts the track relay connected thereto. The light of the lamp 70 in the motorman's cab indicates this sequence of operation. When the right hand contact shoe of the vehicle first engages a righthand ramp of an unoccupied block, the lamp 70 is lighted brightly; as the train progresses and enters the block associated with that ramp and the track relay is shunted, during the short interval of time required for the 85 armature of said track relay to move from its upper position to its lower position, the lamp 70 is extinguished; and when the armature of the track relay reaches its lower position, the lamp 70 will either be re-lighted 90 again dimly by reason of the low voltage, or will remain extinguished. In any event, the motorman is advised by the lighting of the lamp 70 that the contact shoe of the vehicle has engaged a ramp R, and is further advised, by reason of the fact that this lamp is shortly thereafter extinguished, that the armature of the track relay has 95 dropped. 100

Contact shoe indicator.

In order that the motorman may be advised that the contact shoe on the vehicle is 105 adjusted to make proper engagement with a ramp, a lamp 71 is located in the motorman's cab and is included in a circuit which is controlled by the contact shoes of the vehicle, and which is broken when either of these contact shoes is in engagement with a ramp. This circuit may be traced as follows:

Circuit Number Twenty-seven.

Commencing at the local positive wire 180, conductor 194, contact block 15 of the 110 shoe S in its lower position, conductor 195, contact block 15¹ of the shoe S¹ in its lower position, conductors 196 and 301 to the common wire 302 for the lamps 71, and thence through the cab signal cut-in and dimming 115 switch U in the cab occupied by the motorman, along conductor 227 to the common return wire 190.

The lamp 71 is lighted all of the time except while a contact shoe of the vehicle is in engagement with a ramp; and by observing the lamps 70 and 71, the motorman is able to tell when his train passes a ramp whether the contact shoe on the vehicle where the motorman is located is properly adjusted and also whether or not the track relay of the block guarded by that ramp is shunted properly. The lighting and extinction of the lamps 70 and 71 at certain intervals occurs in a cycle, which soon becomes familiar to the motorman, so that he is able to readily detect immediately any failure of the contact shoe and the track relay.

Although I have particularly described the construction of one physical embodiment of my invention, and explained the operation and principle thereof; nevertheless, I desire to have it understood that the form selected is merely illustrative, but does not exhaust the possible physical embodiments of the idea of means underlying my invention.

25 What I claim as new and desire to secure by Letters Patent of the United States, is:

1. In a system for automatically controlling railway vehicles, in combination: means for controlling the movement of a vehicle; 30 a relay for controlling said means; a circuit for governing said relay; means for supplying current to said circuit at different points in the travel of said vehicle; and means governed by said relay for interposing a protective resistance in said circuit when said relay is energized.

2. In a system for automatically controlling railway vehicles, in combination: a vehicle and a track therefor; traffic protecting means on the vehicle including speed controlling apparatus and cab signals; a distinctive signal; and means for automatically rendering said traffic protecting means ineffective and for displaying said signal when the vehicle moves in the direction opposite to the normal direction of traffic.

3. In a system for automatically controlling railway vehicles, in combination: a vehicle and a track therefor; means for controlling the movement of the vehicle having an idle condition and an active condition; cab signals on the vehicle; a distinctive signal on the vehicle for indicating when said cab signals and said first mentioned means are not effective; a relay for automatically rendering said first mentioned means and said cab signals ineffective; means for energizing said relay when the vehicle moves in the direction opposite to the normal direction of traffic; and means for maintaining said relay energized so long as said vehicle moves against the normal direction of traffic and until said first

mentioned means is restored to its idle position.

4. In a system for automatically controlling railway vehicles, in combination: means for automatically controlling the movement of a vehicle; a distinctive signal on said vehicle; a relay adapted when energized to render said means ineffective to control the vehicle and also to display said signal; and manually controlled means for energizing said relay.

5. In a system for automatically controlling railway vehicles, in combination: means for automatically controlling the movement of a vehicle; a distinctive signal on said vehicle; manually controlled means for rendering said means ineffective and for displaying said signal; and means for preventing the operation of said manually controlled means when the speed of the vehicle exceeds a predetermined speed.

6. In a system for automatically controlling railway vehicles, in combination: a vehicle and a track therefor; speed control apparatus; a magnet for controlling said apparatus; a relay for governing said magnet; cooperating devices carried by the vehicle and arranged along the track for controlling said relay in accordance with traffic conditions along said track; and manually operable means dependent on the speed of the vehicle being less than a predetermined low speed for controlling said magnet independently of said relay.

7. In a system for automatically controlling railway vehicles, in combination: a vehicle and a track therefor; speed control apparatus on the vehicle; a relay for governing said apparatus; cooperative devices carried by the vehicle and arranged along the track for controlling said relay; a second relay; an energizing circuit for said second relay; means controlled by said devices for closing said energizing circuit when said vehicle travels in the direction opposite to the normal direction of traffic; and a maintaining circuit for said second relay controlled by said first relay.

8. In a system for automatically controlling railway vehicles, in combination: a vehicle and a track therefor; a device for indicating the actual speed of the vehicle; a device for indicating the permissive speed for said vehicle at different points in its travel; a warning signal; means controlled jointly by said devices for operating said warning signal; an advance signal; and means controlled by said devices for operating said advance signal prior to the operation of said warning signal.

9. In a system for automatically governing the speed of railway vehicles, the combination with a vehicle, of automatic train control apparatus on the vehicle comprising permits

- sive speed means adapted when set into operation to be changed gradually in accordance with the distance traveled by the vehicle and thereby to prescribe limiting speeds for the vehicle during its progress along the track, brake setting means and governing means therefor adapted to cause automatic application of the brakes when the vehicle exceeds the safe speed prescribed, a warning signal in the cab, means for automatically causing operation of the warning signal at a predetermined interval of time prior to the automatic application of the brakes, and means governed automatically in accordance with traffic conditions for controlling the operation of said apparatus. 65
10. In a system for automatically governing the speed of railway vehicles, the combination with a vehicle, of brake controlling means therefor, automatic apparatus adapted to cause operation of the brake controlling means when the speed of the vehicle exceeds certain limiting critical speeds at successive points in its travel, a warning signal, and means governed in accordance with the actual speed of the vehicle and its distance of travel along the track for acting to cause operation of the warning signal when its speed combined with the distance traveled in a predetermined time at that speed would cause said brake controlling means to automatically retard the vehicle, whereby a warning signal will be given a predetermined time in advance of the automatic operation of the brake controlling means so as to enable the operator to reduce the speed of the vehicle and avoid such automatic operation. 70
15. In a system for automatically governing the speed of railway vehicles, the combination with a vehicle, of two control devices thereon each adapted to establish various limiting speeds for the vehicle during its progress along the track, a warning signal governed by one control device, brake controlling means governed by the other device, and means for regulating the operation of both controlling devices in accordance with traffic conditions ahead. 75
20. In a system for automatically governing the speed of railway vehicles, the combination with a vehicle, of two devices thereon each adapted when set into operation to establish two different critical speeds both gradually decreased during the progress of the vehicle, the critical speeds established by said devices having a varying predetermined relation corresponding to an interval of time, a warning signal, brake controlling means, means responsive to the speed of the vehicle and cooperating separately with said devices for controlling the operation of the warning signal and the brake controlling means respectively, and means governed automatically in accordance with traffic conditions for controlling the operation of said devices. 80
25. In a system for automatically governing the speed of railway vehicles, the combination with a vehicle, of brake controlling means therefor, a warning signal, and separate control devices each responsive to the speed of the vehicle and its progress along the track for controlling said warning signal and brake controlling means, one control device being adapted to cause operation of the warning signal at a critical speed which if continued would result in the operation of the brake controlling means by the other device after an interval of time. 85
30. In a system for automatically governing the speed of railway vehicles, the combination with a vehicle, of speed responsive means thereon governed in accordance with the actual speed of the vehicle, a permissive

speed device adapted to change gradually during the progress of the vehicle to impose varying permissive speeds therefor, brake controlling means, means governed jointly by the speed responsive means and permissive speed device for causing operation of the brake controlling means when the actual speed of the vehicle exceeds the prescribed permissive speed, a warning signal, another device adapted to change gradually during the progress of the vehicle to impose varying limiting speeds bearing a predetermined relation to said permissive speeds, means controlled jointly by said another device and said speed responsive means for causing operation of the warning signal, and traffic controlled means for governing the operation of the permissive speed device and said another device in accordance with traffic conditions ahead.

17. In a system for automatically governing the speed of railway vehicles, the combination with a vehicle, of automatic speed control apparatus therefor comprising a permissive speed cam and a warning signal cam each adapted to be moved during the travel of the vehicle, traffic controlled means for governing the movement of said cams, brake controlling means governed by the permissive speed cam, and a warning signal governed by the warning signal cam, said cams being shaped to cause operation of the warning signal prior to the operation of the brake controlling means.

18. In a system for automatically governing the speed of railway vehicles, the combination with a vehicle, of automatic train control apparatus therefor comprising means for establishing a measurable quantity varying in accordance with a prescribed speed-distance curve, other means for establishing a similar quantity varying in accordance with another prescribed speed-distance curve which is in advance of the first curve by increments of distance at different speeds representing a fixed interval of time at those speeds, brake setting apparatus governed by the first mentioned means, and a warning signal governed by the other means.

19. In a system for automatically governing the speed of railway vehicles, the combination with a vehicle, of a cam shaft thereon, gearing adapted to establish a connection from the cam shaft to the wheels of the vehicle, means governed automatically in accordance with traffic conditions for controlling the operative continuity of said gearing, a speed control cam and a warning signal cam operated by said shaft, a speed responsive device governed according to the actual speed of the vehicle, a warning signal in the cab controlled jointly by the speed responsive device and the

warning signal cam, and brake controlling means governed jointly by the speed responsive device and the speed control cam, said cams being of different shape to cause operation of the warning signal prior to the operation of the brake controlling means.

20. In a system for automatically governing the speed of railway vehicles, the combination with a vehicle, of automatic train control apparatus therefor comprising an advanced signal, a warning signal, brake controlling means, and means responsive to the speed of the vehicle and its progress along the track for selectively controlling said signals and brake controlling means, said means causing operation of the advance signal and the warning signal in succession as the vehicle advances at a continuing critical speed prior to the operation of the brake controlling means.

21. In a system for automatically governing the speed of railway vehicles, the combination with a vehicle, of automatic train control apparatus therefor comprising a permissive speed device adapted to change gradually during the progress of the vehicle, a speed responsive device connected to the wheels of the vehicle, an advance signal, a warning signal, and means controlled jointly by said devices for causing operation of said signals successively as the vehicle advances at a critical speed.

22. In a system for automatically governing the speed of railway vehicles, the combination with a vehicle, of automatic train control apparatus for governing the movement of the vehicle, a distinctive signal on the vehicle, means effective to render said apparatus inactive and to display said signal, said means when rendered effective automatically remaining effective until restored, manually controlled means for placing said means in its effective condition, and means partly on the vehicle and partly along the track and controlled automatically in accordance with traffic conditions ahead for governing the restoration of said first mentioned means.

23. In a system for automatically governing the speed of railway vehicles, the combination with a vehicle, of automatic train control apparatus for governing the movement thereof, and adapted when set into operation to continue its control over the vehicle until restored, means for controlling said apparatus in accordance with traffic conditions, and manually controlled means dependent on the speed of the vehicle and effective to render said apparatus inactive when the speed of the vehicle has been reduced to a predetermined low speed.

24. In a system for automatically governing the speed of railway vehicles, the combination with a vehicle, of automatic train

control apparatus for governing the movement thereof, traffic controlled means for governing said apparatus in accordance with traffic conditions, means adapted to be made effective manually when the speed of the vehicle is below a predetermined low speed for rendering the said apparatus inactive to control the vehicle, said means being automatically maintained in its effective condition and being automatically restored by the operation of said traffic controlled means when traffic conditions ahead become safe.

25. In a system for automatically governing the speed of railway vehicles, the combination with a vehicle, of automatic train control apparatus therefor, a normally energized relay for controlling said apparatus, means partly on the vehicle and partly along the track for governing the energization and deenergization of said relay according to traffic conditions ahead, electromagnetic means for rendering said apparatus inactive to control the vehicle, said means being adapted when energized to remain in that condition so long as said relay is deenergized, and manually controlled means for energizing said electromagnetic means.

30. 26. In a system for automatically governing the speed of railway vehicles, the combination with a vehicle, of automatic train control apparatus therefor, a device effective to cause said apparatus to be inactive, means partly on the vehicle and partly along the track for rendering said device effective when the vehicle moves in a direction opposite to the normal direction of traffic, and manually controlled means for also rendering said device effective.

45. 27. In a system for automatically governing the speed of railway vehicles, the combination with a vehicle, of automatic train control apparatus therefor adapted to impose predetermined limitations on the speed of the vehicle, a distinctive signal on the vehicle, a relay adapted when energized to display said signal and to place said apparatus in its inactive controlling condition, and manually controlled means dependent upon the speed of the vehicle being less than a predetermined low speed for causing energization of said relay.

55. 28. In a system for automatically governing the speed of railway vehicles, the combination with a vehicle, of automatic train control apparatus therefor, a device effective to render said apparatus inactive, and impulse transmitting means partly on the vehicle and partly along the track responding to the direction of movement of the vehicle along the track and also to traffic conditions ahead, said means acting to control said apparatus in accordance with traffic conditions while the vehicle is travel-

ing in the normal direction of traffic and to render said device effective when the vehicle travels opposite to the normal direction of traffic, said device being automatically restored to its normal inactive condition by the influence of said impulse transmitting means when the vehicle travels in the normal direction of traffic and traffic conditions ahead are safe. 70

29. In a system for automatically governing the speed of railway vehicles, the combination with a vehicle, of automatic train control apparatus therefor, a distinctive signal on the vehicle, a device adapted to render said apparatus inactive and also to display said distinctive signal, and means comprising cooperating elements partly on the vehicle and partly along the track for governing the operation of said device in accordance with the direction of movement of the vehicle along the track and in accordance with traffic conditions ahead, whereby the train control apparatus will be rendered inactive and said distinctive signal displayed while the vehicle is traveling opposite to the normal direction of traffic and will be automatically restored upon movement of the vehicle in the normal direction of traffic when traffic conditions ahead are safe. 80

30. 90. In a system for automatically governing the speed of railway vehicles, the combination with a vehicle, of automatic train control apparatus thereon including a normally energized electro-pneumatic brake valve, a control relay for governing said apparatus, a manually controlled device for maintaining said valve energized independently of the action of said apparatus, said device after being operated being automatically maintained in that condition until restored, and means governed by said control relay for causing restoration of said device to its normal inactive condition. 95

105. 31. In a system for automatically governing the speed of railway vehicles, the combination with a vehicle, of automatic train control apparatus thereon, means for controlling said apparatus in accordance with traffic conditions, cab signal lamps of different intensities on the vehicle and having their indications governed by said means, and manually operable means for cutting said cab signals into and out of service and for changing their brightness. 110

120. 32. In a system for automatically governing the speed of railway vehicles, the combination with a vehicle, of automatic train control apparatus on the vehicle comprising an electro-pneumatic brake valve and controlling devices therefor, said controlling devices being actuated when the vehicle exceeds certain prescribed speed restrictions, a circuit and a source of current for normally energizing said valve and governed by said control de- 125

vices, a shunt circuit for maintaining said valve energized independently of its controlling devices, and means on the vehicle controlled automatically at points along the 5 track for governing said shunt.

33. In a system for automatically governing the speed of railway vehicles, the combination with a train including a number of vehicles, each equipped with automatic speed 10 control apparatus, of a circuit adapted when energized to cause simultaneous restoration of the apparatus on the several vehicles to their inactive condition and remove the speed restrictions imposed by said apparatus, and 15 a source of current and manually operable key on each vehicle for energizing said circuit.

34. In an automatic speed control system for railway trains including a number of 20 vehicles each equipped with speed control apparatus, a stick relay on each vehicle for rendering the speed control apparatus thereon ineffective, a circuit for causing simultaneous energization of the relays on the 25 several vehicles, a source of current and a manually operable switch for energizing said circuit, and traffic controlled means for governing the stick circuits of said relays.

35. In an automatic train control system 30 for railway vehicles, the combination with automatic train control apparatus on a vehicle, of control means for governing said apparatus in accordance with traffic conditions, a stick relay adapted when energized 35 for rendering said train control apparatus ineffective to govern the vehicle, a pick-up circuit for said relay, manually operable means effective at a predetermined low speed 40 of the vehicle for establishing said pick-up circuit, and a stick circuit for said relay governed by said control means and interrupted when said means responds to clear traffic conditions.

36. In a system for automatically governing the speed of railway vehicles, the combination with a vehicle, of a normally energized electro-pneumatic brake valve adapted 45 to control the application of the brakes of the vehicle, impulse transmitting means comprising elements along the track cooperating with an element on the vehicle and including circuit controlling means tending to de-energize said valve at control points along 50 the track, and a normally de-energized relay on the vehicle governed by said impulse transmitting means and acting independently to maintain said valve energized at said 55 control points when traffic conditions ahead are safe.

37. In a system for automatically governing the speed of railway vehicles, the combination with a vehicle, of a control relay thereon, a circuit for energizing said relay 60 including a resistance, and a shunt for said resistance closed when the relay is deener-

gized, and impulse transmitting means partly on the vehicle and partly along the track for supplying energy to said circuit.

38. In an automatic train control system for railways having signalled territory 70 equipped for the automatic control of vehicles thereon and unsignalled territory not equipped for automatic train control, the combination with automatic train control apparatus on a railway vehicle, of impulse 75 transmitting means partly on the vehicle and partly along the track for governing said apparatus in signalled territory in accordance with traffic conditions, and normally inactive means including the vehicle 80 carried elements of said impulse transmitting means for rendering said train control apparatus ineffective to control the vehicle when it enters unsignalled territory.

39. In an automatic train control system 85 for railways having signalled territory equipped for the automatic control of vehicles thereon and unsignalled territory not equipped for automatic train control, the combination with automatic train control apparatus on a vehicle, of impulse receiving 90 elements on the vehicle adapted to cooperate with means along the track and govern said apparatus in signalled territory in accordance with traffic conditions in advance, a normally inactive device capable of rendering said train control apparatus ineffective to control the vehicle, and means including said impulse receiving element for rendering said device active when the vehicle enters unsignalled territory and for restoring it to its inactive condition depending upon traffic 95 conditions in advance when the vehicle passes from unsignalled territory into signalled territory.

40. In an automatic train control system for railways having signalled territory equipped for the automatic control of vehicles thereon and unsignalled territory not equipped for automatic train control, the combination with automatic train control apparatus on a railway vehicle, of means 110 for rendering said apparatus ineffective to control the vehicle when it enters unsignalled territory, said means when rendered active continuing in its active condition until restored, and means partly on the vehicle and partly along the track for causing the restoration of said first-mentioned means at the entrance to signalled territory to be dependent upon traffic conditions in advance.

41. In an automatic train control system 115 for railways having signalled territory equipped for the automatic control of vehicles thereon and unsignalled territory not equipped for automatic train control, the combination with automatic train control apparatus on a vehicle, of automatic means for rendering said apparatus ineffective to control the vehicle when it enters unsignalled 120 territory.

- territory and for automatically restoring said apparatus to its effective condition when the vehicle again enters signalled territory, said restoration being governed in accordance with traffic conditions in advance. 10
42. In an automatic train control system for railways having signalled territory equipped for the automatic control of vehicles thereon and unsignalled territory not equipped for automatic train control, the combination with automatic train control apparatus on a vehicle, of means including trackway impulse transmitting means for governing said apparatus in signalled territory in accordance with traffic conditions, and means including in part said first-mentioned means for rendering said train control apparatus ineffective to control the vehicle when it enters unsignalled territory 15 and for restoring said apparatus to its effective condition when the vehicle enters signalled territory and reaches a trackway impulse transmitting means in the safe controlling condition. 20
43. In an automatic train control system for railways having signalled territory equipped for the automatic control of vehicles thereon and unsignalled territory not equipped for automatic train control, the combination with automatic train control apparatus on a vehicle, of means partly on the vehicle and partly along the track for governing the operation of said train control apparatus in signalled territory in accordance with traffic conditions, a distinctive signal on the vehicle, and automatic means including in part said first-mentioned means for rendering said train control apparatus ineffective to control the vehicle and for simultaneously operating said distinctive signal when the vehicle enters unsignalled territory. 30
44. In an automatic train control system for railways having signalled territory equipped for the automatic control of vehicles thereon and unsignalled territory not equipped for automatic train control, the combination with automatic train control apparatus on a railway vehicle, of a stick relay for automatically rendering said apparatus ineffective to control the vehicle, and means partly on the vehicle and partly along the track for picking up said relay when the vehicle enters unsignalled territory. 40
45. In an automatic train control system for railways having signalled territory equipped for the automatic control of vehicles thereon and unsignalled territory not equipped for automatic train control, the combination with automatic train control apparatus on a railway vehicle, of a relay for automatically rendering said apparatus ineffective to control the vehicle, means for controlling said relay when the vehicle enters unsignalled territory, and means dependent upon traffic conditions in advance 50
- for restoring said relay to its normal condition when the vehicle passes from unsignalled territory to signalled territory. 55
46. In an automatic train control system for railways having signalled territory equipped for the automatic control of vehicles thereon and unsignalled territory not equipped for automatic train control, the combination with automatic train control apparatus for a railway vehicle including a brake controlling valve and governing contacts therefor, of a relay for shunting said contacts, and means partly on the vehicle and partly along the track for operating said relay when the vehicle enters unsignalled territory. 60
47. In an automatic train control system for railways having signalled territory equipped for the automatic control of vehicles thereon and unsignalled territory not equipped for automatic train control, the combination with automatic train control apparatus on a railway vehicle, of a normally de-energized stick relay adapted when energized to render said apparatus ineffective to control the vehicle, and means partly on the vehicle and partly along the track for energizing said relay when the vehicle passes from signalled to unsignalled territory, said means also acting to de-energize said relay automatically when the vehicle re-enters signalled territory provided traffic conditions ahead are clear. 65
48. In an automatic train control system, the combination with automatic train control apparatus on a vehicle, of a normally de-energized stick relay adapted when energized to render said apparatus ineffective to control the vehicle, means for energizing said relay, and means for automatically de-energizing said relay, said last-mentioned means being governed in accordance with traffic conditions and being effective only when traffic conditions ahead are clear. 70
49. In a system for automatically controlling railway vehicles, the combination with automatic train control apparatus on a vehicle including a normally energized brake controlling valve, a control relay for governing said apparatus, a stick relay for maintaining said valve energized independently of said train control apparatus, means for energizing said stick relay, and a stick circuit for said stick relay including a back contact of said control relay. 75
50. In an automatic train control system for railways having signalled territory equipped for the automatic control of vehicles thereon and unsignalled territory not equipped for automatic train control, the combination with automatic train control apparatus on a railway vehicle, of a normally inactive device for rendering said apparatus ineffective to control the vehicle, and automatic means partly on the vehicle and 80

partly along the track for governing said normally inactive device, said means acting when the vehicle passes from one territory to another and also when the vehicle travels opposite to the normal direction of traffic.

51. In an automatic train control system for railways having signalled territory equipped for the automatic control of vehicles thereon and unsignalled territory not equipped for automatic train control, the combination with automatic train control apparatus of a railway vehicle, of control means for governing said apparatus in signalled territory in accordance with traffic conditions, and automatic means for rendering said apparatus ineffective to control the vehicle when it passes from signalled to unsignalled territory or travels opposite to the normal direction of traffic, said last-mentioned means being governed by said control means to automatically place the vehicle under the control of its train control apparatus when it re-enters signalled territory or resumes its travel in normal direction of traffic provided traffic conditions ahead are safe.

52. In a system for automatically governing railway vehicles, the combination with a brake setting appliance, of speed control apparatus upon the vehicle for operating said appliance dependent on the speed of the vehicle, stop mechanism for operating said appliance independently of speed, means for governing said speed control apparatus and said stop mechanism at control points along the track, and means for rendering said speed control apparatus ineffective to operate said brake setting appliance without affecting the control of the brake setting appliance by said stop mechanism.

53. In an automatic train control system for railways provided with signalled and unsignalled territory, the combination with automatic train control apparatus on a vehicle, of a normally inactive device for rendering said apparatus ineffective to control the vehicle, automatic means for governing said device as the vehicle passes into and out of unsignalled territory, and manually operable means for independently rendering said device active.

54. In an automatic train control system for railways provided with signalled and unsignalled territory over which the vehicles normally travel in one direction, the combination with automatic train control apparatus on a vehicle, of a normally inactive cut-out device on the vehicle for rendering said apparatus ineffective, means for operating said device when the vehicle enters unsignalled territory or travels opposite to the normal direction of traffic, manually operable means for independently operating said device, and means for automatically restoring said device to its normal con-

dition under clear traffic conditions when the vehicle is traveling in signalled territory in the normal direction of traffic.

55. In an automatic train control system for railways provided with signalled and unsignalled territory, the combination with train control apparatus on a vehicle, of a normally deenergized stick relay for rendering said apparatus ineffective, means for automatically energizing said relay when the vehicle enters unsignalled territory, manually operable means for independently energizing said relay, and means partly on the vehicle and partly along the track in signalled territory for controlling the stick circuit for said relay in accordance with traffic conditions.

56. In an automatic train control system, the combination with train control apparatus on a vehicle, of manually operable means for rendering said apparatus ineffective, said means after once being operated automatically continuing in operation until restored, and means partly on the vehicle and partly along the track for automatically restoring said means under clear traffic conditions.

57. In an automatic train control system, the combination with automatic train control apparatus on a vehicle, of a control relay governing said apparatus, means partly on the vehicle and partly along the track for governing the control relay in accordance with traffic conditions, a manually operable device for rendering said apparatus ineffective to control the vehicle, said device after having been once operated automatically continuing in operation until restored, and means whereby said device is automatically restored when said control relay responds to clear traffic conditions ahead.

58. In a railway traffic controlling system, a track divided into blocks, ramps on said track controlled by the conditions of said blocks, a vehicle on said track, a mechanism on said vehicle responding to said ramps and indicating the condition of said track on a plurality of said blocks and means for automatically suspending the operation of said mechanism.

59. In a railway traffic controlling system, a track divided into blocks with a ramp for each block, a portion of said track not divided into blocks having a ramp at the beginning thereof, said ramps controlled by said blocks, a vehicle on said track, a mechanism on said vehicle responding to said ramps and to the condition of said blocks through which said ramps are controlled and means for automatically suspending the operation of said mechanism when entering said portion of track not divided into blocks by the effect obtained from said ramp at the entrance thereof.

60. In a system of the kind described, a

roadway comprising signalled and unsignalled territory, a vehicle adapted to travel thereon, means for automatically controlling said vehicle in signalled territory, in combination with means located at the juncture of said signalled and unsignalled territory, said means co-operating with said controlling means to automatically establish a continuous and distinct indication while said vehicle travels in unsignalled territory.

61. In a system of the kind described, a ground circuit and a stick circuit adapted to automatically control a vehicle in signalled territory, an unsignalled territory pick-up circuit and an unsignalled territory retaining circuit adapted to establish continuous indication that said vehicle is traveling in unsignalled territory.

62. In an automatic train control system for railroads having signalled territory equipped for the automatic control of vehicles thereon and unsignalled territory not so equipped, the combination with automatic train control apparatus on a vehicle for governing the brakes thereof, a relay adapted when energized to render said apparatus ineffective to retard the vehicle, and means partly on the vehicle and partly on the track for automatically energizing said relay when the vehicle passes from signalled to unsignalled territory.

63. In an automatic train control system for railroads having signalled territory equipped for the automatic control of vehicles thereon and unsignalled territory not so equipped, the combination with automatic train control apparatus on a vehicle for governing the brakes thereof, trackway means and vehicle-carried means cooperating to govern said apparatus in signalled territory in accordance with traffic conditions, a relay on the vehicle adapted when energized to render said apparatus inactive to control the vehicle, and normally inactive means for energizing said relay when the vehicle passes from signalled to unsignalled territory, said relay being maintained energized so long as the vehicle is travelling in unsignalled territory.

64. In an automatic train control system for railroads having signalled territory equipped for the automatic control of vehicles thereon and unsignalled territory not so equipped, in combination with automatic train control apparatus on a vehicle for governing the brakes thereof, a stick relay adapted when energized to render said apparatus ineffective to control the vehicle, and means for automatically energizing and deenergizing said stick relay as the vehicle enters and leaves unsignalled territory.

65. In an automatic train control system for railroads having signalled territory equipped for the automatic control of vehicles thereon and unsignalled territory not

so equipped, the combination with automatic train control apparatus on a vehicle, of a control relay governing said apparatus, traffic controlled means for governing the energization of the control relay in signalled territory in accordance with traffic conditions, a stick relay adapted when energized to prevent operation of said train control apparatus, automatic means for energizing the stick relay when the vehicle passes from signalled to unsignalled territory, and a stick circuit for said relay including a back contact of the control relay.

66. In an automatic train control system for railroads having signalled territory equipped for the automatic control of vehicles thereon and unsignalled territory not so equipped, the combination with an electrically operable brake control device, a normally closed vehicle-carried circuit for energizing said device, traffic controlled means for governing said circuit in signalled territory in accordance with traffic conditions, a normally open circuit for energizing said device, a relay adapted when energized to close said normally open circuit, and means for energizing and deenergizing said relay automatically as the vehicle enters and leaves unsignalled territory.

67. In an automatic train control system for railroads having signalled territory equipped for the automatic control of vehicles thereon and unsignalled territory not so equipped, the combination with automatic train control apparatus on a vehicle for governing the brakes thereof, of traffic controlled means for governing said apparatus in signalled territory and including duplicate elements carried by the vehicle on opposite sides thereof, signalling means on the vehicle for indicating when it is travelling in unsignalled territory, a circuit governing the signalling means and controlled by said vehicle-carried elements, and trackway means adjacent to the entrance to the unsignalled territory for influencing said vehicle-carried elements to close said circuit.

68. In an automatic train control system for railroads having signalled territory equipped for the automatic control of vehicles thereon and unsignalled territory not so equipped, the combination with automatic train control apparatus on a vehicle for governing the brakes thereof, of means including duplicate elements carried by the vehicle on opposite sides thereof for governing said apparatus in signalled territory, signalling means on the vehicle for indicating when it is travelling in unsignalled territory, and means including said vehicle carried elements for operating the signalled means when the vehicle passes from signalled to unsignalled territory, said last mentioned means being effective regardless of

which end of the vehicle is ahead as the vehicle enters unsignalled territory.

69. In a system of the kind described, a roadway comprising signalled and unsignalled territory, a vehicle adapted to travel thereon, means for automatically controlling said vehicle when in signalled territory and means responsive to the direction of travel of said vehicle to automatically indicate when said train is passing from signalled to unsignalled territory.

70. In an automatic train control system for railroads having signalled territory equipped for the automatic control of vehicles thereon and unsignalled territory not so equipped, the combination with automatic train control apparatus on a vehicle, of means on the vehicle cooperating with means on the trackway for governing said apparatus in signalled territory, signalling means on the vehicle for indicating when it is travelling in unsignalled territory, and means including in part said vehicle-carried means for automatically operating the signalling means when the vehicle enters unsignalled territory.

71. In an automatic train control system for railroads having signalled territory equipped for the automatic control of vehicles thereon and unsignalled territory not so equipped, signalling means on a vehicle for indicating when it is travelling in unsignalled territory, a stick relay controlling the signalling means, and automatic means partly on the track and partly on the vehicle for energizing the stick relay when the vehicle enters unsignalled territory.

72. In a train control system, a road bed divided into block sections, a vehicle adapted to travel thereon, electro-magnetically controlled means for automatically controlling the movement of said vehicle from said road bed, means for establishing an energizing circuit for said electro magnetic means, said last mentioned means including a pair of interdependent control switches having a plurality of contact positions, said switches being located at opposite ends of said train, a shoe reciprocally mounted and located upon each side of said vehicle, contacts controlled by said shoes and a ramp adapted to cooperate with one of said shoes to effect circuit closure or rupture.

73. In a train control system, a road bed divided into block sections, a vehicle adapted to travel thereon, electro-magnetically controlled means for automatically controlling the movement of said vehicle from said road bed, means for establishing an energizing circuit for said electro magnetic means, said last mentioned means including a pair of interdependent control switches having a plurality of contact positions, said switches being located at opposite ends of said train, a shoe reciprocally mounted and

located upon each side of said vehicle, contacts controlled by said shoes, a ramp adapted to cooperate with one of said shoes to effect circuit closure or rupture, and means for supplying current to said ramp under certain preexisting circumstances.

74. In a train control system, a road bed divided into block sections, a vehicle adapted to travel thereon, means for automatically controlling the movement of said vehicle from said road bed, said means being normally dependent upon the movement of other vehicles in advance of said vehicle when traveling in the normal direction of traffic, and independent of the presence of other vehicles when said vehicle moves in a direction against normal traffic, and means carried by said vehicle for rendering ineffective said functioning of said controlling means whereby a vehicle may move without automatic control in a direction against normal traffic, said last named means including switching devices, some of which are operable manually and others automatically.

75. In a train control system, a road bed divided into blocks, a vehicle adapted to travel thereon, means for automatically controlling the movement of said vehicle from said road bed, said means being normally dependent upon the movement of other vehicles in advance of said vehicle when traveling in the normal direction of traffic, and independent of the presence of other vehicles when said vehicle moves in a direction against normal traffic, and means carried by said vehicle for rendering ineffective said functioning of said controlling means whereby a vehicle may move without automatic control in a direction against normal traffic, said last named means including switching devices, some of which are operable manually and others automatically, 95 all of said devices being interdependently related so as to require being 100 preselected positions before being capable of functioning.

76. In a train control system, a road bed divided into blocks, a vehicle adapted to travel thereon, means for automatically controlling said vehicle from said roadbed when said vehicle is traveling in a normal direction of traffic, and means carried by said vehicle partially automatically and partially manually controlled for controlling said first named controlling means, said means being normally inoperative when said vehicle is traveling in a normal direction of traffic but adapted to operate when said vehicle travels in a direction against the 110 normal direction of traffic.

77. In a train control system, a road bed divided into blocks, a vehicle adapted to travel thereon, means for automatically controlling said vehicle from said roadbed 115

when said vehicle is traveling in a normal direction of traffic, means carried by said vehicle partially automatically and partially manually controlled for controlling said first named controlling means, said means being normally inoperative when said vehicle is traveling in a normal direction of traffic but adapted to operate when said vehicle travels in a direction against normal traffic, and means for indicating the operation of said last named means to the operator of said vehicle.

78. In a train control system, a road bed divided into blocks, a vehicle adapted to travel thereon means for automatically controlling said vehicle from said road bed when said vehicle is traveling in a direction of normal traffic, and means carried by said vehicle for rendering ineffective said controlling means, said means being inoperative to render ineffective said controlling means when said vehicle is travelling in a normal direction of traffic but adapted to render said controlling means ineffective when said vehicle is traveling in a direction against the normal direction of traffic regardless of which end of the vehicle is foremost.

79. In a train control system, a road bed divided into block sections provided with indicating means, a vehicle adapted to travel thereon, means for automatically controlling the movement of said vehicle from said road bed, and energizing circuit which is maintained established between indicating points regardless of the direction of the movement of said train for rendering ineffective said controlling means, a second circuit for rendering ineffective said controlling means, said second circuit becoming effective at the time the train passes by means for giving an indication from the road bed to said train when proceeding under clear signals "with traffic" direction, and a third circuit for rendering ineffective said controlling means when the said train is moving in an against traffic direction, whereby under certain conditions said train may be operated in either direction.

80. In a train control system, a road bed divided into block sections provided with indicating means, a vehicle adapted to travel thereon, means for automatically controlling the movement of said vehicle from said road bed, a stick circuit for rendering ineffective said controlling means when said train is traveling between indicating points, a ground circuit for rendering ineffective said controlling means when said train passes by means for giving an indication from the road bed to said train when proceeding under clear signals in a "with traffic"

direction, and an against traffic retaining circuit for rendering ineffective said controlling means when said train passes by means for giving an indication from the roadbed to said train when proceeding in an against traffic direction, the functioning of said circuits being dependent partly upon manually and partly upon automatically operable means.

81. In an automatic train control system for railroads having signalled territory equipped for the automatic control of vehicles thereon and unsignalled territory not so equipped, cab signal means on a vehicle, traffic controlled means for governing the cab signal means, a relay adapted to extinguish the indications of the cab signal means, and means for automatically controlling said relay as the vehicle enters unsignalled territory.

82. In an automatic train control system for railroads having signalled territory equipped for the automatic control of vehicles thereon and unsignalled territory not so equipped, cab signal means on a vehicle, means on the vehicle cooperating with means on the track for governing the cab signal means in signalled territory in accordance with traffic conditions, and automatic means including in part said vehicle-carried means for extinguishing the indications of the cab signal means.

83. In an automatic train control system for railroads having signalled territory equipped for the automatic control of vehicles thereon and unsignalled territory not so equipped, cab signal means on a vehicle, traffic controlled means for governing the cab signal means, an electrically operable device adapted to extinguish the indications of the cab signal means and establish a distinctive indication to show that the vehicle is travelling in unsignalled territory, and automatic means for actuating said device when the vehicle enters unsignalled territory.

84. In an automatic train control system for railroads having signalled territory equipped for the automatic control of vehicles thereon and unsignalled territory not so equipped, cab signal means on a vehicle, brake control means on the vehicle, a relay controlling the brake control means, an electrically operable device adapted to extinguish the indications of the cab signal means, means for automatically energizing said device when the vehicle enters unsignalled territory, and a stick circuit for said device controlled by said relay.
